UNITED STATES PATENT OFFICE

2,422,805

AIR BLAST CIRCUIT BREAKER

William M. Scott, Jr., Bryn Mawr, Pa., assignor
to I. T. E. Circuit Breaker Company, Philadelphia, Pa., a company of Pennsylvania

Application April 17, 1943, Serial No. 483,387

3 Claims. (Cl. 175—294)

1

My invention relates to circuit breakers and more specifically to high speed outdoor circuit interrupters, particularly adapted for use in connection with high voltage alternating current circuits.

In application Serial No. 410,260, filed September 10, 1941, assigned to the same assignee as the present application, the general organization and detailed construction of a multi-pole high-speed outdoor interrupter in which all of the operating elements were controlled by compressed air and in which the arc quenching as well was performed by an air blast, was described.

My present invention is drawn primarily to modifications and improvements in the various operating elements.

In a pneumatically operated circuit breaker, compressed air may be used both to open and close the contacts. However, when a disconnecting switch is placed in series with the interrupting contacts, the disconnecting switch is to be opened immediately after the interrupting contacts complete the opening of the circuit. Consequently, the interrupting contacts may then immediately be placed in closed position after the disconnecting contacts have opened.

While in prior devices of pneumatically operated circuit breakers, compressed air was used both for the opening and closing operation of the interrupting contacts, my invention contemplates the utilization of a spring member which will normally maintain the interrupting contacts in closed position. The opening air blast will provide sufficient pressure to open the interrupting contacts against the bias of the spring. Immediately upon the opening of the interrupting contacts and the interruption of the arc, the disconnecting contact is opened, whereupon the air blast then stops and since the opening bias of the air blast now no longer counteracts the force of the spring, the spring is operative to reset the interrupting contacts in closed position. The circuit nevertheless remains open since the disconnecting contact is open.

Accordingly, one of the primary objects of my present invention is the provision in a pneumatically operated air blast circuit breaker of a novel arrangement of biasing means for continually urging the interrupting contacts into closed circuit position with substantially a constant force.

A further object of my invention is to provide a novel structural arrangement whereby in an air blast circuit breaker the interrupting contacts of the circuit breaker are normally closed whether

2

the circuit controlled by the circuit breaker is in closed or open condition.

The arrangement of the interrupting contacts so that they are always biased toward closed condition makes possible the simplification of the entire air circuit and the operating mechanisms since specific air operated closing means for the interrupting contacts become unnecessary.

Accordingly, another object of my invention is, in a pneumatically operated air blast circuit breaker having interrupting contacts, the provision of air operated means solely for the purpose of opening the contacts and the utilization of novel automatically operated mechanical means for urging the interrupting contacts back to closed position.

Still another and corollary object of my invention is the provision in a pneumatically operated circuit breaker having interrupting contacts of mechanical biasing means for maintaining the interrupting means in closed position and air-operated means adapted to counteract the force of the mechanical biasing means and overcome the same (momentarily) to temporarily open the interrupting contacts.

In air blast circuit breakers, the opening pressure must be comparatively large to insure high speed opening of the contacts. The shock at the end of the opening stroke often can have deleterious effects on the mechanism.

Accordingly, an object of my invention is to provide novel means for cushioning the end of the opening movement of the movable contacts.

In order to secure high speed operation, I employ a diaphragm valve for controlling the air flow. I have found, however, that such diaphragms when reinforced by metallic plates will leak air to the plate thus tending to separate the diaphragm from its supporting metal plate.

An object of my invention is to provide novel means for securing the diaphragm to its metallic plate.

In circuit breakers in which the contacts are operated to closed position by spring action, it is desirable that at the closing position the spring shall still have a predetermined bias to ensure closing operation.

This type of operation which is essential for maintenance of contact pressure nevertheless creates difficulties in assembly since the force of the spring which is under pressure even in the most extended position of the contacts must be overcome while the parts are being integrated.

Accordingly, it is an object of my invention to provide a novel arrangement of spring-operated

circuit breaker wherein the spring is maintained under pressure even when the contacts are fully closed having means independent of the normal operating elements of the circuit breaker for retracting the spring and maintaining the same in retracted position during test or assembly.

Outdoor circuit breakers are subject to weather conditions including icing conditions which are particularly dangerous where disconnect contacts are necessarily exposed. Various means have previously been utilized in order to cover the disconnect contacts to prevent direct deposit of ice but such means are relatively ineffective owing to the fact that moisture may condense to form ice deposits tending to force the contacts together.

When such ice deposits occur, as they necessarily do, it has previously been deemed essential that a great amount of excess power be applied to the opening of the disconnect contact in order to ensure separation of the elements thereof or it has been regarded as necessary that at least one of the elements of the disconnect contact be made flexible so that relative movement of the parts thereof would tend to crack the ice as the contacts separate.

It is an object of my invention to provide in an outdoor circuit breaker novel disconnect contacts which may be exposed, the elements of which are relatively rigid but which nevertheless separate despite icing conditions.

It is a further object of my invention to provide in a disconnect contact relatively rigid disconnecting elements, at least one of the elements of which, however, has a compound or twisting motion during opening or closing operations which will apply torques to ice formations in different planes in order to cause the ice readily to crack during contact separation or closure.

In heavy outdoor air-blast operated circuit breakers it has frequently been deemed unnecessary to provide arcing contacts owing to the fact that the main contact member compared to the entire operating mechanism was relatively inexpensive and readily replaceable and further owing to the fact that the number of interruptions during the entire life of the circuit breaker was intended to be relatively few (not more than 10 per year).

Since arcing contacts are, however, provided in the present invention in order further to ensure increased life of all of the circuit breaker elements and since the interrupting currents in outdoor air blast circuit breakers of this type are relatively very high, it becomes essential to space the arcing and main contacts from each other in such a manner that during the opening of the interrupting contacts, no possibility will exist of the striking of the arc from the stationary arcing contact to the main contact.

Accordingly, a further object of my invention is in an outdoor circuit breaker the provision of novel main and arcing interrupting contacts operable by the same moving member wherein the arcing contacts are displaced from the main contacts in two planes, that is both longitudinally and laterally.

A further object of my invention is the provision in an arc quencher for an outdoor circuit breaker of improved arc extinguishing and cooling means for arc gases.

Still another object of my invention is to provide a novel arrangement of a multiple number of main bridging contacts.

In air blast circuit breakers, the air pressure tends to move the fixed contacts transversely,

thus reducing contact pressure. It is desirable that the bridging contacts shall maintain full contact engagement until actual separation by movement of the movable contacts is secured.

5 A further object of my invention, therefore, is to provide novel means for preventing transverse movement of the fixed contacts by the air blast.

In general, the invention contemplates a multipole circuit interrupter, the contacts of which 10 separate in a high velocity cooling blast of air. Upon the completion of circuit interruption, that is, upon the extinction of the arc and the removal of the ionized gases and arc products, the potential stresses are removed from the contacts by 15 means of an automatically operable disconnecting switch in series with the interrupter contact, after which the interrupter contacts are closed by mechanical means.

Both the interrupter contacts and the disconnecting switches are operated by compressed air 20 and the relative timing necessary for the operation thereof is obtained by pneumatic control means.

The air supply may comprise an air storage tank charged by means of suitable compressors.

25 The actuation of a main blast valve permits flow of compressed air from the storage tank to separate the breaker contacts, extinguish the arc, and open the disconnecting switches. The disconnecting switch pneumatic operating mechanism is connected by suitable piping with the system for controlling the interrupting contacts.

The operation of the main blast valve is controlled by a high speed pilot valve, supported 30 upon the main valve which may be electromagnetically or manually operated when circuit interruption is desired.

These valves and the main blast valve are of the diaphragm type. They have few relatively 40 light moving members with short strokes and are thus extremely quick acting. Other diaphragm valves are utilized in connection with the main blast valve and its associated trip valves and pneumatically are interlocked therewith.

45 The pneumatic control system employed in connection with our circuit interrupter is particularly advantageous in that relatively few moving parts are required and that the operation thereof requires a minimum of time.

50 The circuit breaker movable arcing contacts are spear shaped members pneumatically operable and each engageable with a pair of spring biased stationary contacts. The main movable contacts bridge the main stationary contacts of each pole so that the circuit may be completed upon closure of the disconnecting switch.

The movable contacts are secured to a piston rod operable by compressed air at a high speed. During circuit interruption, the movable bridge 60 arcing contact is subjected to high acceleration toward the open position and at the time the arcing contacts separate, its velocity is extremely high.

65 The contacts separate in a blast of air which is effective to extinguish the arc, to remove the arc products from the space between the contacts and thus to prevent reestablishment of the arc after the current passes through zero.

70 The circuit breaker is compactly assembled and constructed and, in general, may be supported upon a steel framework. The compressed air storage tank serves as a supporting member for the contact structure of each pole and a control box which includes all of the required relays,

pneumatic devices and the disconnecting switch operating means.

The circuit interrupter is of rugged construction and is adapted to be weather proof in order to be suitable for outdoor installations under all atmospheric conditions. The arcing structure is protected from damage by sleet and snow and is constantly kept dry and in condition for operation by means of an electrically heated stream of air.

In order to insure against failures, provision is made for preventing either the closing or opening of the disconnect switch when the air pressure is too low. The necessary loss of pressure is avoided by preventing closing pressure from being applied to a disconnect switch already closed or opening pressure to a disconnect switch already open. Special provision is made to prevent the application of closing pressure on the disconnect switch while it is being opened.

Figure 26 is a schematic diagram of the piping connection to the various control elements of the circuit breaker.

Figure 27 is a schematic diagram of the electric control wiring for the circuit breaker.

Referring now more particularly to Figures 1 and 2, the circuit breaker comprises essentially an air storage tank 31 and a plurality of circuit interrupting contact structures and disconnecting switches insulatedly supported thereupon. The number of interrupting structures 32 will be dependent upon the particular application of the circuit interrupter and, as illustrated in Figure 1, is a three-pole unit.

Rigidly secured by brackets 36 to the air storage tank 31 is a control box 33 which houses the control valves, electrical means for actuating these valves, and the disconnecting switch operating mechanism. Each interrupter 32 is insulatedly supported upon the unitary structure of storage tank 31 and control box 33 by a pair of insulators proportioned to withstand the mechanical stresses imposed thereupon by the weight of the interrupter 32, the mechanical forces incident to circuit closure and interruption and the high potential stresses imposed.

One of these insulators as will hereinafter be described, is solely a structural member serving to insulatedly space the arc quencher from the ground potential of the storage tank 31 whereas the other of these insulators serves both as a structural member and a conduit for the flow of compressed air from storage tank 31 to arc quencher 32 as required.

The air storage tank is preferably welded to a plurality of metal brackets 34 which in turn are carried high above ground by the metal framework 35. The entire circuit breaker structure is securely anchored at the point of installation by a base 37 of reinforced concrete or the like.

Since it is preferable to maintain the high potential electrical equipment above the reach of the average person, the metal frame 35 may be

relatively high and thus a pair of platforms 41 and 42 are attached to the frame to permit access to the upper portion of the circuit breaker. These platforms may be hingedly supported upon the metallic frame 35 by members 43 and 44.

When in use, the platforms 41 and 42 are horizontally secured by the latches 45 cooperating with pins 40 on the metal frame 35. When not in use the latch may be disengaged and the platforms lowered to the position indicated by the broken lines 41'.

The bus bars 46 and 47 from the external circuits are joined to a terminal 51 on one side of the arc quencher 32 and to the stationary contacts 52 of a disconnecting switch respectively. The circuits between the terminal 51 and the contact 52 is completed through the arc quencher 32 when the contacts therein are engaged and through the engaged contacts of the disconnecting switch.

Essentially, the disconnecting switch comprises a stationary contact 52 which is carried upon insulator 53 mounted upon the metallic bracket 54 which is welded or otherwise secured to the compressed air storage tank 31. The movable contact of the disconnecting switch is supported upon control arm 56 operable by pneumatic means to be described.

The compressed air storage tank 31 is charged through a pipe 61 which enters through the control box 33 and through the main air blast valve as will hereinafter be described. The compressed air may be obtained from an air compressor which may be automatically controlled to maintain the pressure within the tank within predetermined limits.

The control box 33 may be sealed by a pair of doors 62 and 63 so that varying atmospheric conditions will not affect the various control apparatus housed therein. A drain 64 is provided to permit the removal of any moisture which may accumulate therein.

The assembled circuit breaker illustrated in Figures 1 and 2 is designed to be operated outdoors under atmospheric conditions which may include ice and sleet. The structural elements including the arc quencher and the storage tank and control box are all weather proofed to preclude faulty operation and a novel form of disconnecting switch contacts are utilized to preclude binding as a result of the formation of sleet thereupon.

The weatherproof arc quencher 32 and its associated fixed and movable contacts are most clearly illustrated in Figures 3, 3A, 3B, 4, 4A, 5 and 6, 7 and 8 and reference is now made thereto.

The movable contacts comprise first a spear-shaped bridge arcing contact 71 (Figure 7) rigidly secured to a piston 72 operable within a cylinder 73 and second, a parallel pair of current carrying contacts 76 and 76' (Figure 4A).

As illustrated in Figure 4, the arcing bridge contact 71 engages a pair of stationary arcing contacts 74 and 75 which are spring biased toward the movable bridge 71.

In addition, the movable main current carrying contacts 70 and 70' are each engaged with a complementary pair of fixed current carrying contacts 79 and 79' and 80 and 80' respectively, as is best illustrated in Figures 3A and 3B.

When the contacts are in the position illustrated in Figure 4, the circuit between the terminal 39 and the disconnecting switch operating arm 56 is complete, the engagement being made through three distinct sets of electrical con-

tacts, within the throat 75 of a nozzle in the arc quencher 32.

The fixed contacts 74—75; 79—79'; 80—80' are highly conductive metallic members slidable within slotted guides and are connected to flexible conductors which are electrically bonded to the terminal castings 80 and 81.

As illustrated for the right half of the symmetrical contact structure, Figure 3A, members 79'' and 80'' are metallic blocks of rectangular cross-section and are secured by brazing or welding to the respective fixed contacts 79' and 80'. A pair of flexible conductors 77 are secured at one end to each of the rectangular members 79'' and 80'' by the stud and nut assemblies 82 and at the opposed end to the terminal casting 89 by similar stud and nut assemblies 83.

The terminal casting 87 in which the fixed contacts 79 and 80 are secured as are the corresponding contacts 79' and 80' in the casting 89, is highly conductive and is supported above the conduit casting 88 which serves as a guide for the flow of the arc extinguishing and contact interrupting air blast.

An integral extension 91 of the terminal casting 87 supports a plurality of short metallic straps 92 by a plurality of studs and nuts 93. Similarly secured to the lower end of the straps 92 by studs and nuts 94 are two horizontal members 95 electrically connected to the disconnecting switch operating arm 56. The stud and nut assemblies 94 and the straps 95 will be referred to again in the subsequent description of the disconnecting switch.

The line terminal casting 89 is carried by porcelain insulator 96 which in turn is supported upon a beam 97 which extends along the upper surface of the control box 33. The beam 97 serves to carry three insulators such as 96, one for each arc quencher. The conduit casting 88 is similarly supported by means of an insulator 98 upon the air storage tank 31. As illustrated in Figure 4, the insulator 98 contains the hollow axial bore 99 which communicates with the cored passage 100, within the casting 88 and permits the flow of the arc extinguishing air blast.

The insulator 98 as illustrated is spaced from the tank 31 by the member 101 which has an integral extension 102 for rotatably carrying a porcelain insulator 103. This insulator 103 is rotatably supported at the upper end thereof within the bracket 90 and carries the operating arm 105 thereupon as is shown in Figure 14A. This arm 105 coacts with a mechanism to actuate the disconnecting switch operating arm 56 which is pivoted upon shaft 107 extending through the members 98. Rotation of the insulator 103 will cause the operation of the movable contact of the disconnecting switch along the path indicated in Figure 4. The disconnecting switch operating mechanism will be described in greater detail in connection with various other figures.

Referring to Figures 3A and 3B, the stationary contacts 79—79' and 80—80' of each set are axially aligned and are biased towards each other and thus towards the center of the arc chute by the plurality of springs 115. As illustrated, these plunger contacts are each slidably supported in a pair of complementary guides 116 and 117 which are secured to each other by the plurality of bolts 121.

The slotted guides 116 and 117 for each contact are secured by bolts 123 to an inner cover plate 318 that is provided with rectangular perforations 319 to permit the passage of the bodies of the

guides. The plate 310 is in turn secured to casting 89 by bolts 312 and lock washers 313. A similar plate 315 covers a corresponding opening in the complementary terminal casting 87.

A pair of studs 124 and 125 for each stationary contact freely passes through oversize perforations 126 and 127 respectively within the flat extension 79" and are threaded into corresponding perforations 131 and 132 respectively within the slotted guides.

The compression springs 115 are slipped over the studs 124 and 125 and bear against the combination of washer 133 and a pair of nuts 134 which in the well known manner permit the adjustment of the inward bias on the contacts. Thus it will be evident from Figures 3A and 3B that the springs 115 bear against the metallic plates 79" and 80" and the fixed washers 133 to bias the stationary contacts in towards each other and towards the center of the arc chute. The inward motion of each of these contacts is limited by a stop screw 135 which passes through a corresponding tapped perforation 136 in the flat metal plate 79".

The maximum inward movement of the contacts 79" and 80" may thus be predetermined by an adjustment of the position of bolts 135 and this adjustment may be rendered substantially permanent by tightening the lock nut 137. As will be noted in Figure 3B, when the movable contacts 70 and 70' are in the closed circuit position, there is clearance at 141 to assure the maintenance of adequate pressure between the contacts 79-79' and 89-89' and the bridges 70-70' respectively.

Each of the terminal castings 89 and 87 are covered by a plate 142 which precludes the entry of moisture or the like which might cause the faulty operation of the stationary contacts. The fixed arcing contacts 74 and 75 engageable with the spear-shaped movable arcing contact 71 are supported within the terminal castings 87 and 89 respectively in a manner essentially as described above for the fixed contacts 79, 79', 80 and 80'.

Thus the plate 310 contains the upper central rectangular perforation 321 to permit the passage of rectangular guides 322 and 323. These guides are fastened to the plate 310 by the bolts 324. The fixed arcing contact 75 extends through the rectangular guide sections 322 and 323 and as may be seen in Figure 3A, is centrally positioned within the arc quencher 32.

A rectangular metallic member 325 is secured to the outer end of the contact 75 in any suitable manner and is of larger cross-section than the contact itself. As described for the fixed contacts 79 and 80, a stud which is tapped into the slotted guides 322 and 323 extends through a perforation in the rectangular member 325 and retains a compression spring 327 secured at the outer end by washer 328 and nut 329. Accordingly contacts 74 and 75 will be biased inwardly toward the center of the arc quencher 32.

A flexible conductor 337 joins the rectangular plate 325 to the terminal casting 89 where it is secured by bolt 338 to provide positive electrical contact therebetween. The flexible conductor 337 is of smaller cross section than similar conductors 77 since it only carries the full current for the short time interval required for arc extinction.

The arcing contacts 74 and 75 are adjusted by stud 879 and lock nut 860 so that clearance exists between the metallic members 325, and the outer

faces of the rectangular slotted guides when the contacts are in the closed circuit position as indicated in Figure 3B.

From the description above, it will now be seen that the main and arcing contacts assembly is removably mounted in the housing formed by casting 89 and cover 142 and are therefore accessible simply by removing the cover plate 142. This is equally true of the other pair of main and arcing contacts.

The movable arcing contact 71 is preferably a spear shaped copper plate as indicated in Figures 3B, 7 and 8. The lower center portion 151 fits upon an added extension of an operating tube 152 which is welded to the piston 72. A plurality of socket head screws 154 secure the contact 71 to the tube 152.

From the center portion of the contact 71 extend right and left wings, the outer edges 71' of which are surfaced with arc resistant contact material, and as illustrated in the engaged position of Figure 3B, engage the fixed contacts 74 and 75 along contact faces 74' and 75'.

Since the engaged edges of the main stationary and movable contacts 79, 79', 80, 80', 70 and 70' illustrated in Figure 3B maintain the normal current carrying engagement, these edges may be surfaced with extremely low resistance contact material such as silver or the like. The contacts are positioned within the arc quencher such that when the piston rod 152 moves down from the normally closed circuit position shown in Figure 3B the contacts 70 and 70' separate from their associated fixed contacts before separation of contacts 71, 74 and 75 takes place. Hence arcs will be drawn between these last named contacts at points 71''.

From the upper surfaces 71''-71'' the bridge contact 71 tapers inwardly to form a double pointed spear head having a central notch 69. This notch cooperates with a barrier of insulating material as will be described in connection with the structure of the arc quencher and serves to maintain the arcs drawn at the two surfaces 71''-71'' separate during arc extinction.

Inasmuch as all contacts are immersed in a blast of high velocity air during circuit interruption, the edges thereof are tapered as shown in order to provide a streamlined form for precluding excessive resistance to the flow of air thereacross.

During the closing movement of the contact arm 152, the movable contact 71 first engages the lower edges of the fixed contacts 74 and 75 along its upper sloping surfaces 71''. Continued upward movement of the contact 71 forces the two fixed terminals 74 and 75 outwardly, against their normal bias.

In the final closing movement of piston rod 152, the main current carrying contacts 70 and 70' engage their respective fixed contacts and so divide the full line current among the three sets of contacts in each pole of the arc quencher.

The movable contacts are operable by piston 72 which is slidably arranged within the cylinder 73 and as indicated in Figure 7 is in the closed circuit position and as indicated in Figure 8 is in the open circuit position. The piston 72 may be actuated from below by a spring when in the position indicated in Figure 8 and by air entering from above when in the position indicated in Figure 7. Its operations will hereinafter more specifically be described.

As illustrated in Figure 4, the arc quencher 32 is supported upon insulators 96 and 98 by the

metal castings 51 and 88. Between the castings 51, 89, 88 and 87, the arc quencher is a composite structure of insulating blocks arranged to permit the operation of the stationary and movable contacts and to permit the most effective exhaust of the hot gases and arc products resulting from circuit interruption.

As illustrated in Figures 1 and 2, the various components of the arc quencher are supported between two plates 161 and 162 of weather resistant phenolic insulation. The different insulating blocks utilized to form the arc quencher are secured to these insulating plates by a plurality of through studs such as 163 as indicated in Figure 3 which are sheathed in insulating bushings 164.

The outer blocks of phenolic insulation 161 and 162 are substantially trapezoidal and a peaked porcelain or slate roof 180 as indicated in Figure 1 covers the arc quencher. The contact operating cylinder 73 is secured to an open ended cylinder support 165 which is supported between the phenolic insulation blocks by the through studs 166 and their associated insulating bushings. The opening 167 in the cylinder support 165 permits the influx of high pressure air to drive the piston 72 down into the cylinder.

As previously mentioned, high pressure air may flow through the duct 99 in the insulator 98 and through the cored passage 100 in the casting 88. As seen in Figure 3, a pair of insulating blocks 171 and 172 also supported between the phenolic insulation blocks provide a substantially rectangular continuation of the passage 100 and communicates as illustrated in Figure 4 with the open end of the cylinder support 165.

The insulating blocks 171 and 172 may be formed from impregnated wood or a similar relatively light durable insulating material. An insulating block 174 of similar material to that utilized for blocks 171 and 172 is supported between the phenolic insulating layers 161 and 162 to fill the space between the cylinder 73 and the terminal casting 51. The perforations 175 in the lower flanges of the castings 51 and 88 provide means for bolting these castings to similar flanges on the insulators 98 and 99.

Directly above the terminal castings 89 and 87 are two pairs of insulating blocks 176 and 177, (Figure 3) spaced by a vertical central barrier 178. The barrier 178 is notched at 180 to receive a complementary extension of a similar arc dividing barrier 179, which in turn sets into a notch 181 in a transverse arc splitting barrier 182.

The arc splitting barrier 182, as best illustrated in the exploded view of the arc quencher, Figure 4A, extends downwardly from the roof of the arc quencher and contains a V-shaped notch 183 in the central section thereof, complementary to the notch 69 in the spear-shaped arcing contact 71. Rectangular notches 184 extending from the apex of the notch 183 in the barrier 182 are also provided to permit the snug fit between contact 71 and barrier 182 as shown in Figure 3.

It is evident, therefore, that during circuit interruption, two distinct arcs will be drawn between the tips of contacts 71 and the fixed arcing contacts 74 and 75 and that these arcs will be separated throughout interruption by the barrier 182. It is further evident that upon the assembly of the arc splitting barriers 178 and 179 and 182, that the arc quencher will be divided into four similar chambers, enclosed by the outer sheets of phenolic insulation 161 and 162.

This quadrilateral division of the arc quencher extends from the roof to the lower end of the barriers 179, where they fit into a slot 185 at the upper surface of an interrupting chamber 5 comprising a plurality of blocks of an extremely arc resistant material such as soapstone. This soapstone interrupting chamber which protects the less resistant members of the arc quencher will be described in greater detail in later paragraphs.

The arc splitting barrier 182 continues downward below the barriers 179 and terminates as indicated in Figure 3 at the apex 186 of the open ended cylinder support 165. The rectangular slot 187 continuing beyond the V-notch 183 in the central arc splitting barrier 182 provides clearance for the movable contact assembly carried upon the piston rod 152.

As previously described, high pressure air may enter the arc quencher from the air storage tank 31 through the conduit 100. This air in travelling up through the arc quencher will first be split into two streams or loops by the arc splitting barrier 182 and then further split into four streams or loops by the barriers 179 which are at right angles to the barrier 182.

This air carrying with it the arc products incident to circuit interruption will be exhausted from the arc quencher in a manner to be described.

The highly arc-resistant, restricted area surrounding the contacts within the arc quencher is provided by eight blocks of soapstone so arranged and so machined as to produce first a convergent air channel, then two divergent air channels and then four divergent air channels communicating with the four exhaust chambers provided by the upper intersecting arc barriers.

This novel arrangement of soapstone blocks 40 shields the arc and in addition provides means for sheathing the slotted guides associated with the fixed arcing and main current carrying contacts.

Figures 5 and 6 are exploded perspective views 45 of the left side of the soapstone arcing chamber and clearly indicate the various machining operations which must be performed upon the blocks to provide the necessary channel and guide.

The views, Figures 5 and 6, are of the same 50 blocks but taken from opposite sides of the arc quencher. The right hand soapstone blocks are identical units with the exception that the members are rotated 180 degrees about a vertical axis.

In Figures 5 and 6 the soapstone blocks 191 55 and 192 form the enclosing outer members of the four block structure.

The inwardly sloping notches 195 and 196 in the enclosing members 192 and 191 respectively have faces 197 and 198 which are in the same 60 plane as the faces 199 and 200 of the central soapstone blocks 194 and 193 respectively. The plane of the faces 197, 198, 199 and 200 slopes inwardly so that upon assembly, they form a divergent channel leading to the central throat 65 76 of the arc quencher assembly.

Notches 201 and 202 in the soapstone blocks 192 and 194 respectively are milled to accommodate one pair of the slotted contact guides 116 and 117. The depth of these slots is predetermined so that a snug fit is obtained between the slot and the slotted guide assembly. However, there is no interference between the walls of the soapstone slabs and the fixed contacts 80 and 81. Similar slots 203 and 204 are provided in 70 the soapstone blocks 193 and 191 to accommodate

the complementary slotted guide contact carrying assembly. Machined slots 295 and 296 are provided in the central blocks 194 and 193 respectively to enclose the central slotted guide assembly for carrying the fixed arcing contact 75.

It is thus evident that the contact 74 is in slot 297 formed when the blocks 193 and 194 are in contact and hence is positioned directly within the central restricted throat 76 of the arcing chamber. The air blast velocity at this point will be a maximum and hence arc interruption will be efficient and reduced to a minimum of time.

From the throat 76 which surrounds the fixed arcing contacts 74 and 75 and the movable spear-shaped arcing contact 71, the air channel diverges upwardly. This divergence is accomplished by the machined recesses 210 and 211 in the central soapstone blocks 193 and 194 respectively. Centrally located tapering recesses 212 and 213 provide, when the blocks 193 and 194 are in contact, a channel of rectangular cross-section which diverges to the right of a vertical central axis as viewed in Figures 5 and 6.

This channel is maintained distinct from a similar channel formed by sloping recesses 214 and 215 by partitions 216 and 217 in the blocks 193 and 194. The outer faces of these partitions coincide when the blocks are assembled and hence two channels are formed emerging from the throat 76. As previously mentioned, one of these channels is diverted to the right as viewed in Figure 6 and the channel formed between sloping recesses 214 and 215 is diverted to the left as viewed in Figures 5 and 6.

These channels are also maintained apart from similar channels which are formed in the right hand section of the arc quencher and on the opposite side of the arc splitting barrier 182, the edges of which are securely positioned upon the faces 221 and 222 of the blocks 191 and 192 respectively.

The divergent channels extending from the throat 76 in the central part of the soapstone shield, continue through tapers 223 and 224 in the blocks 191 and 192. The barriers 179 and 170 which extend downwardly from the uppermost portion of the arc quencher enter the soapstone assembly through the notches 225, 226 and 227 in the central members 193 and 194. Therefore, at the lower face 228 of these notches, intercommunication between the channels diverging from the throat 76 is impossible.

Since the arc barriers 179 extend into the soapstone enclosure as above described, it is therefore desirable to notch these barriers as indicated at 230 in Figure 3, so that the channels extending upwardly from the throat will be unimpeded by the presence of sharp angular edges of this barrier.

Vertical recesses 231 and 232 have been machined into the block 191 and 192 over the entire length thereof. It is evident therefore since, as previously mentioned the arc splitting barrier 182 rests upon the faces 221 and 222 of the blocks 191 and 192, that air gaps will exist between the faces 231 and 232 of the recesses and the arc barrier 182.

These air gaps function to increase the surface leakage distance across the barrier and hence prevent re-ignition of the arc subsequent to extinction. Also since these air gaps are in the path of the converging channel between the faces 195 and 196 of the high pressure air inlet, there will be a flow of high pressure air up through these air gaps during interruption to ensure the thorough

cleansing of arc products formed therein. A conducting arc product bridge between opposed fixed arcing contacts is essentially impossible.

When the movable contacts are in the closed circuit position indicated in Figure 3B, the movable bridge arcing contact substantially seals the throat 76 of the soapstone assembly. Upon actuation of the trip circuit to initiate contact separation, a blast of air will enter the lower chamber of the soapstone blocks, while simultaneously acting upon the piston 72 to cause downward motion of the contacts.

However, as the high pressure air flows into the arc quencher through channel 199, the pressure within the arc quencher will build up considerably. Since the fixed contacts 74, 75, 79, 80 and 80' enter into the soapstone assembly, there will be a force exerted upon the inner faces of these contacts by the high pressure air, and will tend to cause the fixed contacts to move outwardly against the bias of their compression springs. The separation of the fixed and movable contacts by this force would be a highly undesirable condition, since there would be arcing between the fixed current carrying contacts, and the movable current carrying contacts, which previously described need not be faced with arc resistant material.

In order to preclude the motion of the fixed contacts under the influence of the incoming blast of air, the soapstone members 193 and 194 have been provided with the rectangular milled slots 233 and 234 which extend horizontally from the center of the arc quencher and communicate with the interior of the terminal castings 89 and 97.

Clearly, therefore, upon the initiation of an air blast, the pressure which is built up within the soapstone enclosure will also be transmitted to the interior of the terminal castings and hence to the outer faces of the fixed contacts. The presence of high pressure air at both inner and outer surfaces of the fixed contacts will thus neutralize the tendency for movement of the fixed contacts under any influence other than their associated compression springs.

The air blast pressure which is built up within the soapstone throat 76 immediately prior to downward movement of the movable contact is of considerable assistance in circuit interruption. This results from the fact that air under pressure has a considerably greater dielectric strength than air at atmospheric pressure. Hence the higher pressure air will tend to minimize the arc and to eliminate the possibility of re-ignition subsequent to interruption.

The insulating blocks 191, 192, 193 and 194 are positioned between the terminal castings 89 and 97. Bored slots such as 235 are therefore provided to receive the heads of bolts which secure the contact slotted guide assemblies to the plates 319 and 315 covering the interior of the terminal casting.

To further protect the upper portions of the outer sheets of phenolic insulation 161 and 162, pads of fibrous material resistant to arc products are inserted as at 236 in Figure 3. These sheets are cut to fit the contours of the space provided and the lower edges thereof nest within slots 237 and 238 of the outer soapstone blocks 191 and 192.

Air leakage from the arc quencher which ordinarily might be considerable due to the number of joints therein is reduced by the introduction of a number of keyways or slots 239 at the edges of the different insulating blocks. These keyways

upon assembly are filled with sealing compounds such as a wax or the like.

At the upper central end of the four divergent passages which extend from the throat of the soapstone enclosure, there are positioned four sets of metallic conduits 241, Figure 3. The outer surface of these conduits 241 is substantially circular for a ninety degree arc between the plane faces 242 and 243 (Figure 4A). These curved conduits 241 are formed by alternately stacking metallic plates 244 and spacing plates 245, which have extensions 246. All these plates 244 and 245 are perforated at points such as 247 to accommodate studs, and the entire assembly is clamped by nuts which engage the outer threaded portions of the studs.

The alternate metallic plates 244 which comprise the conduit assembly thus provide effective means for cooling the exhausting blast of air as it flows from the soapstone enclosure.

The exhaust end 243 of the conduits 241 are sealed by spring biased shutters 251 (Figure 3). These shutters are hinged at an extension 252, suitably secured to the conduit 241. The springs which bias the shutters 251 to the closed position are not shown but may, of course, be included in the hinges 252 in the well known manner. Extensions 253 are provided at the hinge side of the conduit 241 to guide the conduit into position and nest in corresponding slots in the barrier 178. These conduits 241 are secured to the outer sheets of phenolic insulation 161 and 162 by screws which pass through the insulating sheets and into tapped members 254 as shown in Figure 3.

The spring biased shutters assist in building up a pressure within the arc chute during circuit interruption and hence as previously described assist in the extinction of the arc by maintaining the air at a pressure greater than atmospheric.

Since the shutters will swing open rapidly upon the introduction of air into the arcing chamber, rubber shock absorbers 255 are secured to the barriers 178 by a plurality of screws 256.

Air exhausting from the conduits 241 enters chambers which are formed between the insulating blocks 176 and 177 and the roof of the arc quencher. From these chambers the air is exhausted to the atmosphere through louvres 257 which are suitably cored in the cast exhaust flues 258. These louvres 257 slope downwardly from the chamber between the insulating blocks 176 and 177 and the arc quencher roof and, hence, it is evident that the louvres and the shutters coact to form an arcing structure which will preclude the entry of foreign objects such as leaves, birds, wasps and the like.

Located above the cooling conduits 241 and adjacent the arc splitting barrier 162 are a plurality of insulating blocks 260 suitably curved as illustrated in Figure 3. These blocks complete the insulating structure to which the roof of the arc quencher is secured by a plurality of studs 261 which thread into the barriers 178 and 179 and the outer insulating sheath 161 and 162. Nuts threaded upon these studs will serve to secure the roof.

Referring now to Figures 7 and 8, it may be seen that the movable contact assembly is carried upon a piston rod 152 operable within the air cylinder 73. The member 152 is a hollow cylindrical tube and has secured to the upper end thereof an inverted cup-shaped member 265. The cup-shaped member 265 has a bifurcated extension 266 which is slotted at 267 to provide

means for centrally positioning the bridge contact 71.

Thus, as indicated in Figure 8, the movable bridge contact 71 is positioned between the tines of the bifurcated extension 266 and securely fastened thereto by the socket head screws 154. The cup-shaped member 265 is secured to the operating tube 152 by means of a plurality of set screws 268 which extend from the lower face of the slot 267 into tapped holes in a cross-bar 270 welded into the upper center of the tube 152.

The casting 265 is provided with two contact carrying pads 271, Figure 3A welded thereto. The pads are slotted at 272 to provide rectangular depressions for securing and positioning by socket head screws 273 the main current carrying movable contact 70 and 70'. The contacts 70 and 70' are parallel and are spaced at a distance equal to the spacing of the fixed current carrying contacts 79 and 89.

The air cylinder 73 consists of a main hollow structure sealed at the lower end by the integral head 73'. A cylindrical boss 275 extends from the integral head 73 and is drilled and tapped at 276 to receive the threaded end 277 of a cylindrical rod 278. The diameter of the rod 278 is somewhat greater than the diameter of the threaded end 277 and hence a shoulder 279 is formed which bears against the inner lower face 30 of the cylinder. To secure the rod 278 within the cylinder, the nut 280 and the lock washer 281 are utilized as shown.

The piston 72 is a webbed casting and includes an integral re-entrant flange 282 at the upper edge thereof. The outer cylindrical surface of the piston 72 and the inner cylindrical surface of the cylinder 73 have been machined to provide a smooth cooperating sliding fit. The cylindrical surface of the piston is turned to include a plurality of substantially rectangular grooves 283 which act to minimize air leakage over the edges thereof.

A rectangular key 284 is secured to the inner wall of the cylinder 73 by means of a plurality of screws 285 which pass through perforations in the cylinder wall. A corresponding rectangular slot 297, as seen in Figure 8, is cut into the surface of the piston 72 and accordingly rotation of the piston and its integrally associated movable contacts is impossible.

The lower end of the tube 152 is received by a central bore 286 in the piston 72, whereat it is secured in any suitable manner.

The axial cylindrical rod 278 acts to position a compression spring 287 which is fixed at the lower end by the integral cylinder head 73' and at the upper end of the tube 152 by the bar 270 which is welded across the opening of tube 152.

The central bore 288 within the rod 278 is provided to pass a rod which may be screwed into the boss 274 in the cross-bar 270 at the upper end of the tube 152. The rod may then be pulled downward and maintained in a position to cause separation of the contacts. With the contacts separated, a breakdown test in the arcing chamber may be made.

Because the high gaseous pressure which may develop at the upper face of the piston 72 may produce a dangerously fast piston blow against the cylinder head 290, a valve air passage is provided between the upper face of the piston and the cylinder by a slot formed between the wall of the cylinder 73 and the piston head 72. During a portion of the downward stroke, air from the upper face of the piston passes into the cylinder.

der to cushion the piston stroke. During other portions of the stroke, this opening is closed as the piston moves beyond the slot.

The cylinder head 73' is surfaced on the inside by a rubber disk 290 which acts as a buffer to cushion the downward movement of the piston 72. A counterbore 291 is provided in the wall of cylinder 73 to receive a rubber gasket 292. This gasket is sealed into the cylinder by the cylindrical flange 293, and its integrally associated circular extension 294. The gasket 292 absorbs the shock incident to the termination of the upward motion of the piston 72 and with the gasket 290 serves to define the upper and lower limits of travel of the piston and its associated contact.

A bearing for the contact operating assembly is provided in the form of a casting 295 having a central web structure terminating in the upper bearing 296, as illustrated in Figures 3, 7 and 8. This web structure permits the flow of air upwardly therethrough when the piston is moving in this direction.

The cylinder 73 and the bearing casting 295 are joined together to the cylinder support 165 by four through bolts 298, Figure 4, which pass through axially aligned lugs 299 on the cylinder and into corresponding tapped perforations in the cylinder support 165.

The unitary structure of cylinder and cylinder support 165 is then secured to the arc quencher by the studs 166 which pass through holes 301 in the cylinder support 165 and through corresponding holes in the outer phenolic plates 161 and 162.

From Figures 7 and 8 it is evident that the piston 72 and its associated piston rod and movable contact are normally biased to the position indicated in Figure 7.

The event of a circuit fault will result in the initiation of a blast of air which will enter the arc extinguishing structure through the duct 100. This air will flow down through the cylinder support 165 and through the webbed bearing casting 295 and force the piston 72 down against the bias of its spring.

The piston will remain in the position illustrated in Figure 8 as long as the air blast continues but immediately upon cessation of the flow of high pressure air, the spring 287 will return the contact assembly to the position shown in Figure 7 and cause first, the engagement of the arcing contacts 74 and 75 with the bridge contact 71, and second, completion of the main circuit by the engagement of bridge contacts 70 and 70' with their associated fixed main current carrying contacts.

It is evident, therefore, that the compression spring 287 must at the end of the stroke still provide a force sufficient to engage the contacts, overcoming the normal friction at the engaging surfaces thereof.

As previously described, the contacts of each pole are in series with a disconnecting switch which opens after the interrupting contacts during opening and which closes after the interrupting contacts during circuit closure so that the breaker contacts may be free to operate immediately, if such is required.

As illustrated in Figures 11, 13, 13A, 14 and 14A, each pole of the disconnecting switch includes a pair of rotatable arms 56, each carrying a movable contact 800 at the outer edge thereof.

Each of the two fixed contact structures mounted upon the insulator 53 is shielded by a casting 802 which, as illustrated at Figures 11,

13 and 14, comprises side enclosures 803 and 804 and a rear wall 805. Integral extensions 806 and 807 of the side walls 803 and 804 extend downwardly to form the foot 808 which has the horizontal extension 811. A plurality of bolts 812 extend through suitable perforations in the horizontal extension 811 and are tapped into corresponding perforations at one end of the horizontal tie-bar 813. Bolts 814 passing through the center of the tie-bar 813 secure the entire structure of two fixed contact assemblies and tie-bar to the upper portion of the insulator 53.

The open top of the protective casting 802 is covered by a highly conductive cover plate 815 to which the terminal extension 816 is suitably secured. A vertical flange 817 is secured to the cover plate 815. The lower surface of the flange 817 is cut in the form of an inverted V, having a central apex 818. Hence, it may be seen that condensation collecting upon the flange 817 will tend to drain downwardly along the lower surface of the flange to the outer walls of the protective casting 802. This simple means for the removal of condensation will preclude the collection of moisture upon the fixed contact assemblies to be described and hence will preclude faulty operation as a result of ice accumulation.

Within the protective casting 802 an integral reinforcing rib 821 (Figure 14) is provided with the horizontal flange 822 extending between the walls 803 and 804. A plurality of screws 823 extend upwardly through tapped holes in the flange 822 and through clear holes in a metallic bar 824 which rests upon the upper surface of the flange 822. For reasons which will hereinafter be described, the holes in the bar 824 are somewhat larger than the outer diameter of the screws 823, thus permitting a limited movement of the bar 824 normal to the screws 823.

Secured to the bar 824 by a plurality of screws 825 is a rectangular metallic plate 826 which rests against two inwardly extending ribs 827 and 828 in the side walls 803 and 804 of the protective casting 802. The plate 826 is received at its upper end by a slotted stud 831 extending upwardly through a perforation 832 in the cover plate 815. The perforation 832 is suitably tapped to receive the inverted cup-shaped retaining member 833, which is threaded at the lower end thereof. A lock nut 834 secures the retaining member 833 to the cover plate 815.

A compression spring 835 is retained within the member 833 and bears against the upper portion of the slotted stud 831, thus biasing plate 826 downward and causing the engagement of the metallic bar 824 and the transverse flange 822.

Clearance is provided at 836 between the sides of the rectangular plate 826 and the walls of the protective casting 802. It may therefore be seen that although the plate 826 is restrained, a limited transverse motion is possible.

The plate 826 is slotted to permit the passage of six rectangular contact bars divided into two parallel sets 837, 838 and 839 spaced properly to receive the movable contact 800 positioned upon the contact carrying bar 56.

Each set of three contacts 837, 838 and 839 is made integral by a tie bar 840 which extends across the contacts and is secured to each by suitable bolts and nuts 841 which pass through aligned perforations in tie bar and contacts.

In addition, the contact of each parallel set 837, 838 and 839 are biased towards each other by an arrangement including studs 842 and 843

which extend through perforations in opposite parallel contacts.

Thus, as is most clearly indicated in Figure 13, compression springs 844 are slipped over the extending ends of the studs 842 and 843 and are brought to bear against the contact bars 837, 838 and 839 by a cap 845 threaded upon the studs.

The studs 843 serve in addition, to orient the contact bars by loosely passing through aligned perforations in a channel member 846 secured by a plurality of screws 847 to the face of the rectangular plate 816. At the forward end, the contact bars 837, 838 and 839 are spaced by the heads of bolts 848 tapped into perforations 849 in the upper faces of contact bar 837 and 838.

At the rear of the contacts 837, 838 and 839, the inward bias continuously exerted by the compression springs 844 is carried by the rectangular extension 850 of the terminal extension 851. The terminal extension is, as illustrated in Figure 14, secured by welding or brazing to the lower face of the cover plate 816.

In order to provide good electrical contact between the engaging portions of the contacts 837, 838 and 839 and the downwardly extending terminal extension 851, the contacts are recessed at 852 and are provided with silver inserts engageable with similar silver faces 853 upon the extension 850 of the terminal member.

In order to prevent arcing during the closing of the disconnect switch caused by intermittent separation of bars 837, 838 and 839 from terminal extension 851, a pigtail connection between these contacts and the terminal member 851 is provided by a flexible conductor 854 which is secured by bolts 855 to each of the contacts 837, 838 and 839 and by bolts 856 to the bottom of the terminal extension 851. The use of the pigtail prevents arcing and therefore makes it possible to use a metal of high conductivity for the contact faces 853 which otherwise would be pitted by the arcing.

The terminal extension 851 also provides additional means for limiting the vertical motion at the back of the fixed contacts which complete one of the two circuits provided for each disconnect switch pole.

Thus, as illustrated in Figure 13, studs 857 are tapped into suitable perforations in the terminal extension 851. As shown in Figure 14, there are two such studs positioned above and below each set of contacts 839 and 837 respectively. These studs thus will limit vertical motion at this end of these contact bars.

The upper contacts 833 of each set extend beyond the lower contacts 837 and 838 in order to provide for an arcing contact as will now be described.

Thus, inserts 860 are secured by socket head screws 861 in recesses of the ends of contact bars 839. The inserts 860, as best illustrated in Figure 11, have curved inner surfaces converging at the contact bars 833. The curved surfaces are provided so that the movable contact 899 will be received in a funnel-like contact arrangement to facilitate self-alignment of the contacts.

The inner surfaces of the contact inserts 860 are covered with layers of metal extremely resistant to arcing and register with similar inserts 863 of arc-resistant material carried upon the movable contacts 899.

The movable contacts 899, as illustrated in Figures 13, 14, 13A and 14A, comprise parallel blocks of highly conductive material 870 securely bolted into position within recesses 873 in the contact carrying arm 56.

The side faces of the contact bars 870 are surfaced with silver layers 875 engageable with corresponding silver inserts 876 upon the contacts 837 and 838. The layer of arc resistant metal 863 upon the movable contact is somewhat thicker than the layer of silver 875 as is best shown in Figure 13 and hence it is clear that upon clockwise wise movement of the contact carrying arm 56, as viewed in Figure 14, the lower edge of the arc resistant metal 863 will first contact the arcing tips 860 and upon continued rotation will cause the engagement of the contacts 838 and 837 with the silver surface 875 to form an effective electrical junction therewith.

Upon contact separation, that is, upon counter-clockwise rotation of the contact carrying arm 56, as viewed in Figure 14, the silver-to-silver contact between the bars 837 and 838 and the movable contact bar 870 will first separate and separation will then be completed when the arc-resistant layer 863 separates from the arcing tip 860, and any arc drawn at this point will not damage the arc-resistant surfaces.

The over-all thickness of the movable contacts 899 is somewhat larger than the spacing provided between contact bars 837, 838 and 839 and hence the engagement of these contacts will cause an outward movement of the inner ends of the fixed contact bars.

Since the novel mounting means provided for the fixed contact bars permits considerable twisting, any ice which has formed thereon will readily be cracked and dislodged. A similar condition will exist upon the separation of the movable and fixed contacts.

As in the case of the main contact within the arc quencher, the disconnect switch may be required to carry a considerable current. For this reason, each pole of the disconnect switch has been constructed of two distinct terminals connected in parallel. Thus to engage the fixed contacts of each pole, two movable blades 58 are provided.

As is best illustrated in Figures 11, 13A and 14A, the two blades 58 for each pole are rigidly spaced at the centers thereof by a sleeve 890 and a stud 891 which extends through suitable perforations 892 in each blade and is secured at each end by a nut and lock washer 893.

The parallel blade assembly 58 is pivotally supported upon a shaft 167 which in turn is carried in corresponding perforations in extensions 885 of a casting 900.

The casting 900, as illustrated in Figures 13A and 14A includes a plurality of lower lugs 901 and upper lugs 902 which are suitably drilled to pass a corresponding number of bolts which thread into the conduit casting 86 of the arc quencher, as illustrated in Figure 4.

The casting 900 also includes an integral ribbed extension 903 having a machined flat surface 904, which by bolts 905 supports a rectangular bar 906.

A sheet metal housing 907 is secured to the bar 906 by a plurality of nuts and bolts 908. The housing 907 serves to shield the movable contacts 899 from sleet as does the housing 802 for the fixed contacts.

The central lower section of the casting 900 is provided with a bearing 910 which rotatably secures a rod 911, an integral extension of a casting 912 that caps the upper end of the rotatable insulator 103. The cap 912 is secured to the insulator 103 by bolts 913.

Between the extensions 885 of the casting 900,

the shaft 107 is enclosed by a suitably bored sleeve 920 that serves to maintain the proper spacing of the extensions 895.

Electrical contact is made from the terminal casting 87 to the contact carrying bars 56 through the conducting bars 92 and 95, the latter of which are bent as illustrated in Figure 13A, and are suitably perforated to permit the passage of the shaft 107.

Included between the rotatable arms 56 is a casting 925 which, as will hereinafter be described, is a member of the operating linkage. The casting 925 is rigidly secured in any suitable manner to the arm 56 at the engaging surfaces 926. Extensions 927 of the casting 925 are perforated and fit over shaft 107 between the extension 995 of the casting 990 and the operating arms 56.

Thus, by tightening nuts 928 upon the threaded extensions 929 of the shaft 107, the members 95, 56, and 925 and 920 and 990 are brought into good electrical contact. A spring washer of conventional form 930 is utilized at each end of the shaft 107 to provide an electrical contact while permitting proper rotation of the arms 56 about the shaft 107.

All of the members enclosing the shaft 107 may, if desired, be silver-plated at this point in order to provide positive electrical contact at all times.

In order to cause clockwise and counterclockwise rotation of the contact operating arms 56 so as to engage or disengage the disconnecting switch contacts, a crank 105 is secured to the upper end of the shaft 911 which, as previously mentioned, is secured to the rotatable insulator 103.

A stud 931 extends upwardly from a perforation 932 in the crank 105. Located upon the stud 931 between washers 933 is a rectangular block 934 which is perforated at 935 to provide a smooth fit about the stud 931. A nut 936 retains the block 934 upon the stud 931.

The rectangular block 934 is in turn rotatably carried upon shaft 937 between the tines 938 of a link 939. It is thus evident that the link 939 may rotate about shaft 937 and about shaft 931. The link 939 also has tines 940 which rotatably secure a second rectangular block 941 about shaft 942. Another shaft 944 at right angles to shaft 942 passes through the rectangular block 941 and is secured within the bearing extension 946 of the casting 925, which as previously mentioned is fixed to the parallel bar assembly 56.

Thus the three links 105, 939 and 925 and their associated rectangular blocks 934 and 941 provide a double universal mechanism so that rotation of the shaft 911 and hence crank 105 will cause rotation of the contact arms 56 about the shaft 107.

As view in Figure 13A, clockwise rotation of the crank 105 will result in displacement of link 939 to the right and accordingly will cause rotation of the contact arms 56 about the shaft 107 so that contacts 890 rise to the position within the shield 907, as is illustrated in Figure 4.

On the other hand, if crank 105 rotates counterclockwise about its axis, as viewed in Figure 13A, the contacts 890 will descend to the closed circuit position illustrated in Figure 11.

Rotation of crank 105 is accomplished as previously mentioned by rotation of insulator 103 which in turn is obtained by pneumatic means contained within the control box 33 and actuated during the closing and opening movements of the interrupting contacts. The actual mechanism for causing the rotation of insulator 103 in accord-

ance with circuit conditions will be described more thoroughly in later paragraphs.

As described in connection with Figures 4 and 13A, the bars 92 are suitably secured to the conductors 95 by a plurality of studs and bolts 94. However, as illustrated in Figure 13A, one of these studs for each group is tapped into a perforation in a boss 950 integral with the casting 990. This stud 951 extends outwardly through the contacting bars 92 and 95 and is secured at the outer end by the nut 94.

By the manipulation of the nut 94 and an additional nut 952 the bar 95 may be moved toward or away from the casting 990. This will serve to vary the nature of the surface contact 953 between the bar 95 and the rotatable arm 56. Therefore, it is evident that by the adjustment of nuts 94 and 952, the position affording the closest surface contact 953 may be attained. At this point the bolts 94 and 952 may be secured permanently. An additional nut 954 provides means for locking the stud 951 to the casting 990.

Rotation of contact carrying arms 56 is obtained by pneumatic means contained within the control box 33.

Referring to Figures 9 and 10, the pneumatic cylinder 362 is illustrated within the control box 33. The cylinder 362 is rigidly secured to the upper panel of the control box 33 by a pair of brackets 363.

The linkage for causing the required movement of the disconnecting switches is operatively arranged with respect to the cylinder 362 and passes above the control box and above the storage tank 31 as illustrated in Figures 2 and 9 and is joined to the plurality of insulators 103 rotatably mounted as previously mentioned.

The pneumatic cylinder 362 comprises a hollow cylindrical member terminated at either end by a cylinder head and has an opening pipe 365 entering at one end and a closing pipe 366 entering at the other end. These pipes, through the control mechanism, which will be described, supply air from the main storage tank 31 to cause axial movement of the piston 367 contained within the cylinder and its attached piston rod 371. Axial displacements of piston rod 371 will cause rotation of the crank 372 by the connecting rod 373 which is pivotally attached to both the crank 372 and the piston rod 371. Thus a pair of pins 374 and 375 pass through holes drilled in the connecting rod and the crank and the piston rod and permit the rotation of the crank 372.

The crank 372 is supported upon a vertical shaft 376 which is rotatably supported in bearing 377 which is fixed to the walls of the control box 33. The shaft 376 extends above the control box 33 and carries at its upper end an additional crank 381 as illustrated in Figures 2 and 10. This crank 381 which is fixedly mounted upon a squared section of the shaft 376 is hingedly attached to a connecting rod 382 which is joined to a crank 383 extending from a metallic member 384 secured by a plurality of bolts 387 to the insulator 103 of the middle pole of the breaker as is also illustrated in Figures 2 and 4.

The connecting rod 382 is preferably constructed from a plurality of elements as shown in Figure 9 in order to facilitate the assembly and adjustment thereof. Thus it may be seen from Figure 9 that displacements of the piston 367 under the influence of air entering through either the opening pipe 365 or the closing pipe 366 will cause rotation of the insulator 103 which is rotatably mounted as illustrated in Figure 4.

Thus as illustrated in the integral extension 102 of the insulator support 101 contains a cylindrical projection which is perforated to accommodate a stud 385 which is secured therein by means of lock nut 386 (Figure 4). The weight of the insulator is carried by a ball thrust bearing while a needle bearing carries the horizontal forces incident to operation. These bearings are not illustrated but may be of conventional form.

Thus the insulator 103 may rotate upon fixed stud 385 under the influence of the connecting rod 382 which is joined to the bifurcated crank 383 by a pin 391 as illustrated in Figure 9. To provide for simultaneous operation of all the disconnecting switches, the cranks 393 on each one are interconnected by means of rods 392 which extend therebetween and are pivotally secured to each one by the pins 394. Thus rotation of insulator 103 through the agency of crank 381 will cause the corresponding rotation of all of the disconnecting switch insulators through the agency of the cranks 393.

The operating linkage illustrated in Figure 9 is biased towards the open or closed circuit positions by an overcenter compression spring 395. This spring 395 is supported upon a rod 346 which in turn is fixed to a member 397 at one end thereof. The member 397 is pivotally carried upon an extension 401 of the crank 372. The opposite end of the rod 346 freely passes through a perforation 402 in a rotatably mounted support 403 as illustrated in Figures 9 and 10. Both the members 397 and 403 are of a greater diameter than the shaft 346 and the compression spring 395 bears against the surfaces of each of these members thus normally tending to maintain the crank in the position to which it was last operated.

As illustrated in Figure 9, the position of the disconnecting switch operating linkage corresponds to the closed circuit position.

To provide for manual operation of the disconnecting switches, a metal block 405 is welded or otherwise secured to the crank 372. A perforation 406 in the block 405 permits the insertion of a metal rod, with which the crank 372 and thus the entire linkage may be operated.

Clockwise rotation of the crank 372 corresponds to movement towards the open circuit position of the disconnecting switches. The disconnecting switches are operable from the rotatable insulators 103.

The operation of this circuit breaker will now be described and reference is made to Figure 26 which is a schematic representation of the various circuit breaker elements and the control members therefor. The various valves required for the operation of this air blast circuit breaker will first be described generally and their relation to the control system will be indicated. These valves will then be described with reference to the more detailed drawings thereof.

In Figure 26, each of the circuit breaker arc quenchers and operating cylinders are represented schematically by the cylindrical member 450 which exhausts to the atmosphere at the upper end thereof. The contact operating piston 72 carries the piston rod 152 to which the bridge contact 74 is secured. The bridge contact is in operative relation with respect to the inwardly biased stationary arcing contacts 74 and 75 on each pole. The fixed current carrying contacts are not shown in this figure.

The air storage tank 31 is charged through the supply line 451 from a compressor which is not

illustrated. However, as already mentioned, this compressor may be of any conventional form having an air drier and oil filter in the air line to preclude the entrance of impurities into the storage tank 31. A series of valves which will later be described are inserted in the supply line to afford the proper control of the air flow.

Compressed air from the storage tank 31 may upon the actuation of the proper control means enter the blast manifold 452 which communicates with each of the arc quenching units 450 through the port 100 which, as previously described, is a cored passage within the terminal casting 88.

The introduction of air through the blast manifold 452 will cause downward motion of the piston, a blast of air around the contacts and consequent circuit interruption. A pipe line 365 interconnects the blast manifold and the disconnecting switch cylinder 362 and as has been described in connection with Figure 9, the admission of compressed air through pipe 365 will cause displacement of the switch piston 367 and consequent opening of the disconnecting switches.

The opposite end of the disconnecting switch cylinder 362 communicates with an unloading valve through pipe line 366. The admission of compressed air through this pipe will cause the closing of the disconnecting switches.

The blast manifold 452 communicates with the interior of the air storage tank 31 across a circular valve seat 455 schematically illustrated in Figure 26. This valve seat is normally engaged by a flexible diaphragm 457 which precludes the entry of compressed air. However, the displacement of diaphragm 457 to the left as viewed in Figure 26 will permit the introduction of high pressure air into the blast manifold 452 to cause downward movement of the piston 72 and displacement of piston 367 towards the left or open circuit position to open the disconnecting switch contacts.

The principle of operation of the main blast valve in which the operable member comprises the flexible diaphragm 457 will now be described with reference to the simplified schematic diagram thereof.

The valve diaphragm 457, which is preferably circular, is fixed across a circular opening 461 in the air storage tank 31. A dome shaped member 462 encloses the outer face of the flexible diaphragm 457 and an auxiliary pipe line 463 from the storage tank charges the dome space 465 between member 462 and diaphragm 457 with high pressure air and thus the pressure within the dome 465 is normally maintained at a value substantially the same as the pressure within the main tank 31.

If the air within the blast manifold 452 is at atmospheric pressure then the compressed air within the tank 31 will exert a force upon an annular section of the inner face of diaphragm 457. However, the air pressure within the dome 465 will exert a force over the entire surface of the same diaphragm and thus the resultant force will act to seal the blast manifold 452 across the circular seat 541.

Actuation of the diaphragm 457 may be obtained by reducing the air pressure within the dome 465 whereby the air pressure within the tank 31 will force the diaphragm from its seat 541 and discharge through the blast manifold.

The action of this type of valve is extremely rapid due to the relatively large force which is exerted upon the annular area of the diaphragm

subsequent to the release of the air within the dome and the lightness of the moving parts.

Air may be released from the dome 465 by opening vent 466 by automatic or manual means.

Since the auxiliary air line 463 constantly feeds the dome 465 it is necessary to make the vents of relatively large area in order that the air pressure within the dome will decrease rapidly when the vent is opened. Since the main blast valve of this circuit breaker is necessarily large due to the comparatively large interrupting capacity thereof, an additional diaphragm valve is utilized to effect the release in dome pressure.

Thus an auxiliary flexible diaphragm 467 is supported in a suitable manner over the vent 466. An auxiliary dome shaped member 468 then encloses the outer face of the diaphragm and is of a greater diameter than the vent 466.

The specific nature of the valves utilized in connection with the air blast circuit breaker structure just described and in connection with the control system illustrated in Figure 26 will now be described in connection with Figures 9, 10, 12 and 15 to 25 inclusive.

As illustrated in Figures 9 and 10, with the exception of the main blast valve which is situated directly upon the air storage tank 31, the valves are supported upon the metal frame of the control box 33.

As illustrated in Figures 10, 12, 15 and 17, the main blast valve comprises a cylindrical casting 525 which extends through an opening 526 in the air storage tank 31. The junction between the air storage tank and the body of the main blast valve is secured by a weld 527 as illustrated in Figure 17.

An annular flange 531 contains a ring of holes 532 through which bolts 533 pass and secure the control box 33 thereto.

The body of the main blast valve comprises an outer cylindrical shell and an annular valve seat centrally supported in it. As illustrated in Figures 12, 17 and 18, the circular valve seat 534 is supported by four radial arms 535-538 extending from the outer cylindrical body 525.

The valve body comprising the outer cylindrical frame 525, the annular member 534 and the radial members is preferably a single metallic casting as illustrated in the figures. The inner walls of the annular member 534 first converge from the circular rim 541 toward the inside of the tank and then diverge and includes at the inner end thereof of the three cored sockets 542, 543 and 544 into which pipes 548, 549 and 550 are inserted and welded thereto as illustrated in Figure 12. These pipes, as illustrated in Figures 4 and 9 extend from the sockets 542-544 through the inside of the tank 31 to the ducts 130 which lead to the arcing chambers of the individual arc quenching units.

Thus it may be seen that the annular member 534 is the equivalent of the schematically illustrated blast manifold 452 of Fig. 26.

In addition to the three pipes which emanate from the central annular member 534 to the arc quenching units, a duct is provided for supplying air to the disconnecting switch operating cylinder 362. This is most clearly illustrated in Figure 17 in which the annular member 534 and one of the supporting radial arms is illustrated in cross-section.

A cored passage 545 extending through the radial supporting member 537 opens into the passage through the annular member 534. The passage 545 extends through the main cylindrical

portion of the body of the blast valve and terminates in a boss 546 which is tapped at 547 to receive a piping connection 551. As illustrated in the general assembly view of the control box,

5 Figure 10, the pipe line 365 extends from the boss 546 of the main blast valve to the disconnecting switching operating cylinder 362. In order to enhance the flow of high pressure air through the contact 545 during the opening operation of 10 the circuit interrupter, a cylindrical scoop 552 is secured to the junction 553 where the duct 545 enters the annular member 534. The mouth of the scoop 552 is directed toward the circular rim 541 of the annular member 534.

15 The body member 525 of the main air blast valve is covered by a circular member 554, a flange 555 of which fits against the outer portion of the valve body.

20 A gasket 556 is inserted between the valve body 525 and the cover 554 to prevent air leakage. The members 554 and 525 are secured to each other by a plurality of bolts 557, as illustrated in Figures 15 and 17, which pass through perforations in the valve head 554 and into threaded holes in 25 the cylindrical member 525.

The valve head 554 is recessed at 561, as shown in Figures 17 and 18, to permit opening movement of the diaphragm 457 and corresponds with the dome-shaped member 462 described in connection with the control system, Figure 26. The valve diaphragm 457 normally engages the circular valve seat 541 of the annular member 534 and prevents the flow of air from the inside of the tank 31 through the annular passage 562 between 30 the cylindrical body 525 and the annular member 534 to the blast manifold and the three pipes emanating therefrom.

35 The circular valve diaphragm 457 is supported upon the valve dome 554 by a retaining ring 563 and a plurality of screws 564. The screws 564 pass through aligned openings within the retaining ring 563, the diaphragm 457 and the valve dome 554.

40 In order to prevent slippage and radial movement at the periphery of the diaphragm a plurality of circular teeth 565 of V-cross-section are machined into the engaging surfaces of the retaining ring 563 and the dome 554. These teeth are caused to grip the diaphragm securely when 45 the screws 564 are tightened. The diaphragm 457 itself may, depending upon the particular application, be of relatively large diameter and thus considerable mechanical strength is required to withstand the forces imposed due to high pressure air.

50 Furthermore, it is desirable to prevent excessive distortion of the diaphragm 457 during operation, and hence the diaphragm is preferably of laminar construction as illustrated in Figures 17, 17B, 17C.

60 As shown, the diaphragm comprises a pair of 55 flexible rubber sheets 457' and 457'' between which is secured a circular sheet of metal 566 for mechanical bracing. The metal sheet 566 is of greater diameter than the circular valve seat 541 of the annular member 534. To provide a suitable bond between the flexible rubber sheets and the metallic member 566 the metallic member is roughened and inserted between the flexible sheets prior to the vulcanization thereof. Hence 65 when the diaphragm is completely vulcanized, it comprises an integral rubber sheet in which a metallic member is securely embedded. A plurality of small holes 570 in the rubber sheet 457'' are formed on a radius less than that of the annular valve seat 541. These holes are formed to 70

preclude distortion of the rubber sheet 457" due to seepage of high pressure air from the dome side of the diaphragm through the rubber around the edge of the steel plate to the low pressure area within the manifold. This air is released through holes 570.

The edge 563' of the retaining ring 563 and the corresponding edge of the dome shaped member 554 have been rounded, as indicated in Figures 17 and 18, to prevent cutting of the diaphragm surfaces during the movement thereof.

The diaphragm 457 is normally biased toward the annular member 534 by a plurality of spring loaded plungers 571. As illustrated in Figures 15, 17 and 18, these plungers are retained within hollow cylindrical members 572 which are secured within tapped holes 573 in the dome shaped member 554. The cylindrical retainers 572 comprise a section of hollow tubing which is sealed at the outer end by a cap 574 by welding or any other suitable means.

The caps 574 are, as illustrated in Figures 15 and 17, machined to provide a rectangular cross-section in order to facilitate the use of a wrench for securing the retainers in place.

The plungers 571 are normally acted upon by compression springs 575 which bear against a flange 576 at one end of the plunger and against the inner surface of the cap 574.

The plungers 571 are preferably hollow in order to reduce the weight thereof and consequently the kinetic energy developed during their motion.

It is to be noted that the plungers 571 press against the reinforced portion of the diaphragm 457 and are directed toward the valve seat 541 of the annular member 534.

The strength of the springs and the number of plungers employed to bias the diaphragm will be dependent on the force desired. These springs are symmetrically located with respect to the diaphragm in order that the biasing force be uniform over the valve seat.

The dome 554 of the main blast valve is centrally drilled to accommodate the trip valve 582 which is supported thereupon.

As indicated most clearly in Figures 15, 16, 17 and 18, the trip valve is a compound magnetically operated unit and operates generally in the manner described in connection with the schematic diagram, Figure 26. The trip valve comprises a diaphragm 583 of reinforced construction which is in all respects similar to that described and illustrated in connection with the diaphragm 457.

The diaphragm 583 is engageable with a circular valve seat 584 which is an integral circular projection of the surface of the valve head 554. The diaphragm 583 is enclosed within a dome shaped member 585 and is secured thereto by a clamping ring 586 and a plurality of screws 587 similar to the securing means illustrated and described in connection with the main valve diaphragm 457.

The dome shaped member 585 is in turn secured to the main dome 554 by a plurality of screws 591 which pass through holes in lugs 592 extending from the valve dome 585 and thread into bosses 593' on the surface of the valve head 554, as is more particularly illustrated in Figure 17.

The valve diaphragm 583 is spring biased toward the valve seat 584 by a plurality of plungers 588 and springs 594. The retainers for the springs and the plungers may, as most clearly illustrated in Figure 18, be cored passages 595 in the valve dome 585.

It is to be noted that the annular area 596

75

which encircles the valve seat 584 on the underside of the diaphragm 583 is at atmospheric pressure at all times whereas the inner circular area of the diaphragm 583 is normally at the pressure within the dome between the valve head 554 and the diaphragm 457.

In order to permit maximum air velocity (thus minimizing operating time) a streamlined nozzle member 601 (Figures 17 and 18) is secured within the central bore 597 of the valve head 554 by a plurality of screws 602 which pass through the outer edge of the member 601 and engage in threaded holes in the valve dome 554.

As schematically indicated in Figure 26, a magnetically operated pilot valve is used to initiate the tripping action. An additional annular valve seat 605 is provided which, as shown in Figures 17 and 18 is an integral extension of the trip valve head 585. The air passage 606 is nozzle shaped and discharges in the direction of the valve seat 605. This valve seat 605 is normally engaged by a layer of valve seat material 607 which is imbedded and secured within the recess 611 in a plunger 612.

The plunger 612 is a magnetic member manually or automatically operable within the solenoid 613, which is wound upon a suitable form having a stationary core 614 and enclosed by magnetic member 615. The electromagnetic trip valve structure is supported upon a plurality of integral extensions 616 on the valve head 585. Thus, as illustrated in Figures 15, 17 and 18, a plurality of screws 617 pass through the magnetic members 615 and into tapped perforations in the extensions 616.

The magnetic plunger 612 is normally biased against the valve seat 605 by a compression spring 621 which is retained in axially aligned bores in the plunger and the magnetic stop 614. A hollow screw 622 provides an adjustment for spring pressure and also a bearing for the plunger rod 623 which is secured to the plunger 612 by the screw threads 624.

Thus it may be seen that the layer of valve seat material 607 normally seals the passage 606 and that this passage may be opened to the atmosphere by manually displacing plunger rod 623 to the right as viewed in Figures 17 and 18 or by energizing the solenoid 613.

Under normal operating conditions of this circuit breaker, the air storage tank 31 is charged with relatively high pressure air and the dome shaped space 625 between the valve heads 554 and the valve diaphragm 457 and the correspondingly shaped space 626 between the valve head 585 and the valve diaphragm 583 are maintained at the full tank pressure.

Referring now to Figure 10, compressed air enters the circuit breaker mechanism through pipe 451 corresponding to the similarly numbered pipe in the schematic drawing, Figure 26. The manually operated valve 627 may be utilized to shut off the flow of air to the breaker. A check valve 631 is inserted in the pipe line 451 in order to prevent the release of air from the storage tank during inoperative periods of the air compressor.

Air flows into the storage tank 31 from the pipe line 451 through the T-connector 632 and through the cored passage 633 in the cylindrical valve structure 525 as illustrated in Figure 19. The passage 633 extends to the inside of the storage tank 31 from a boss 634 on the trip valve body. The outer end 635 of the passage 633 is tapped to permit the insertion of the piping connection 632.

Accordingly, it may be seen that when the valve

627 is open, high pressure air may flow into the storage tank 31, the pressure of which may be read upon the conveniently disposed gauge 636 in the pipe line 451.

The dome 625 is normally charged by air at storage tank pressure. This is accomplished through suitable pipe lines as is most clearly illustrated in Figures 15 and 17. Accordingly, a drilled passage 641 through cylindrical valve structure 525 connects the interior of the tank and a passage 642 which is drilled in a rib 643 in the valve head 554.

The sealing gasket 556 is perforated at 644 and the valve head 554 is similarly perforated at 645 to permit continuous passage between the ducts 641 and 642. Since the passage 642 is drilled through the rib 643, it may be sealed from the atmosphere by a plug 646 screwed into the outer opening thereof.

The passage 642 communicates with a reduced diameter passage 651 in the rib 643 through a reducing plug 652 which is secured by the screw threads 653. This provides means for inserting an air filter for precluding the entry of dust and the like, which might cause faulty sealing of the valves, or may be replaced by a unit having a bore of different diameter to alter the rate of flow of the air. The passage 651 enters the annular space between the opening 597 in the valve head 554 and the discharge nozzle 601.

As shown in Figures 17 and 18, clearance is provided at 654 between the inner wall of the valve seat 584 and the streamlined member 601. Accordingly, air at tank pressure may flow through the passages 641, 642, 651 and back through streamlined member 601 and into the dome 625.

In a like manner the dome shaped space 626 is charged by air at tank pressure. Thus referring to Figures 15 and 16, it may be seen that a passage 655 is drilled through the cylindrical valve member 525 and connects the interior of the air storage tank 31 with a drilled passage 656 in a rib 657 of the valve head 554.

A plug 661 seals the outer end of the passage 656 to prevent the escape of high pressure air to the atmosphere.

A passage 662 at right angles to the passage 656 passes through the valve diaphragm 583 and its associated retaining ring 586 and communicates with a passage 663 in an extension 664 of the trip valve head 585. The passage 663 is sealed by a plug 665 threaded into the outer end thereof. A bushing 668 in passage 662 passes through the hole in the diaphragm and is inserted in counterbore 669 at each end to prevent the clamping of the diaphragm from closing this opening.

A hollow cylindrical member 666 is non-rotatably supported within a reduced diameter of the passage 663 and extends into the nozzle shaped passage 666 in the trip valve head 585. The inner end of the cylindrical member 666 is drilled at 667 in order that air flow therethrough is directed towards the valve seat 605.

An air filter 671 is retained within the duct 663 to remove foreign particles from the air stream and may be replaced when desired by removing plug 665.

Thus it may be seen that if the interior of the blast manifold 452 is at atmospheric pressure while the tank 31 is charged with air at high pressure, the valve diaphragm 457 will be acted upon by high pressure over the entire right surface as viewed in Figure 17 when the trip valve is closed whereas only an annular section of the

left hand surface will be acted upon by high pressure. Thus the air will bias the valve diaphragm 457 into engagement with its valve seat 541 and so prevent the flow of air between the storage tank 31 and the blast manifold.

Similarly, under normal operating conditions, the plunger 612 will seal the nozzle shaped passage 606 and permit the air pressure within the dome 626 acting upon the full area of the diaphragm 583 to cause it to engage the valve seat 584. In this instance, however, the left hand surface of the valve diaphragm 583 will have an annular surface at atmospheric pressure and a central circular area at the pressure of the main dome 625.

The compression springs 575 and 594 and their associated plungers 581 and 593 will maintain the pilot valve and diaphragm valve against their seats even if the tank 31 is discharged and at atmospheric pressure.

Upon energization of the solenoid coil 613 or upon manual displacement of plunger rod 623 to the right as viewed in Figures 17 and 18, the plunger 612 would be displaced from its valve seat 605 and vent the dome 626. The venting action will take place at a much greater rate than the rate of air flow into the dome through the opening 667 illustrated in Figure 16 since the discharge opening in the valve head 585 is of considerably greater area. However, in order to minimize the interference between the outflowing air and the incoming air, the inlet passage 666 has been arranged as illustrated in Figure 16 in order that the inflowing air may have an aspirating effect and assist in the venting of dome 626.

This will increase the speed of operation of the circuit breaker as will be described later in greater detail.

The rapid drop in pressure in the dome 626 due to the displacement of plunger 612 will permit the high pressure air in dome 625 to displace trip valve diaphragm 583 to the right as viewed in Figures 17 and 18 against the action of the compression springs 594.

In a manner similar to that described for the trip valve, the release of air from the dome 625 will be accelerated by the aspirating effect exercised by the high pressure air discharge to the atmosphere through the narrow annular passage 654 between the member 601 and the valve seat 584. Consequently the actuation of plunger 612 will result in the displacement of valve diaphragms 583 and 457 and permit high pressure air in the tank 31 to flow over the valve seat 541 into the blast manifold 452 to the individual arc quenchers and to the contact operating cylinders.

Furthermore, since the scoop 552, illustrated in Figure 17 is in the path of the high pressure flow in the blast manifold, the disconnecting switch piston 367 will be displaced to open the disconnecting switches.

It will be noted that high pressure air will continue to flow into the domes 625 and 626 if the plunger 612 is maintained in its displaced position but as the discharge area is considerably greater than the inlet area no appreciable pressure can be built up to cause closing of the valves. If the plunger 612 is released, if manually operated by releasing the plunger 623 or by deenergizing the coil 613 if electrically operated, the compression spring 621 will cause the closure of valve seat 605 and hence cause an increase in pressure in the dome 626.

This will in turn cause diaphragm 583 to move

against its seat 584 and hence cause the pressure within the dome 625 to build up to full tank pressure to close the main diaphragm 657. Thus the flow of high pressure air to the arc quenchers will cease.

In order to prevent the accumulation of condensed moisture within the dome 625, a continuous passage is provided interconnecting the interior of the tank and the base of the dome. As illustrated in Figure 20, this passage is formed by drilling a passage 671 in the dome, communicating with the annular passage 672 which represents the normal clearance between the dome 554 and valve body 525.

Since the passage 671 is at the very lowest point of the dome 625, any moisture which accumulates in the dome will drain through the passages 671 and 672 and into the tank 31 along surface 673. At suitable time intervals the tank itself may be drained.

As previously mentioned in connection with Figure 10, the storage tank is charged by air through pipe line 451. If the tank is initially discharged and it is desired to place the circuit breaker in condition for operation, the valve 627 is opened to permit the flow of air from the compressor.

The spring biased plungers 531 and 593 illustrated in Figures 17 and 18 maintain engagement between their associated valve diaphragms and valve seats. This is essential in order to prevent loss of air through the main blast valve until sufficient pressure is built up in the valve domes to hold the valves closed.

The springs need only be strong enough to compensate for the pressure drop of the air flowing through the passages to the domes 625 and 626 since both domes are charged simultaneously. The charging rate of the domes are controlled by the removable bushings 652 and 666 in the radial passages entering therein. These bushings may be replaced by others having a smaller or larger orifice as required.

The control valves, namely a closing valve and an unloading valve, are supported within the control cabinet 33 and are operable from the common compressed air tank 31.

Referring now to Figures 23, 24, 25 and 26, the construction and operation of the closing valve 509 will be described.

In order to complete the circuit through this circuit breaker, it is necessary, since the main contacts within the arc quencher are engaged, merely to close the disconnecting switch.

The operation of the closing valve will control the flow of air from the storage tank 31 through the pipe 501 to the unloading valve through pipe 502. During normal operation, the unloading valve will permit the flow of high pressure air from the closing valve to displace the disconnecting switch piston to cause rotation of insulator 103 and corresponding closure of the disconnecting switch.

The closing valve comprises essentially a main circular body casting 682 having an inner annular extension 683. Between the outer cylindrical walls of the casting 682 and the annular extension 683, there is formed an annular chamber 684 which is filled in at two points by extending radial bosses 686 and 697.

As illustrated in Figure 23, the boss 686 is drilled at 698 to provide a passage into which pipe 591 is threaded. Thus air coming from the storage tank 31 through the pipe 501 communi-

cates directly with the inner cylindrical chamber 684 of the circular valve body.

A third boss 691 extending from the cylindrical valve body 682 is similarly drilled at 692 and receives the threaded pipe 502 which, as illustrated in Figure 26, leads to the unloading valve.

The perforation 692 communicates directly with the annular chamber 681 but does not directly communicate with the central chamber 684. The upper circular end 693 of the annular inner extension 683 provides a valve seat normally engaged by a circular diaphragm 694. The diaphragm 694 is of construction similar to the main blast valve diaphragm previously described and comprises a pair of rubber disks vulcanized about a smaller diameter steel disk 695 to provide an integral flexible unit. The diaphragm 694 is retained upon a flange 696 of the main valve body 682 by a dome shaped member 697. This dome shaped member 697 is secured to the main valve body flange 696 by a plurality of screws 700 which pass through corresponding perforations 701 in the dome 697, the diaphragm 694 and the flange 696.

A plurality of integrally cast wells 702 provide means for retaining a corresponding number of plungers 703 having flanges 704 at the lower end thereof. These plungers 703 are normally biased against the diaphragm by compression springs 705 which are retained as illustrated in Figure 24.

It is evident, therefore, that these circularly placed spring biased plungers 703 will normally tend to maintain a fixed relationship between the circular diaphragm 694 and the edge 693 of the annular extension 683. The radial boss 687 is drilled at 708 to provide a passage leading to the central chamber 684. The outer end of the perforation 708 is sealed by a plug 709 suitably tapped into the outer edge thereof.

Similarly a boss 710 on the dome shaped member 697 is radially drilled to provide the passage 711 sealed at the outer end by the plug 712. A drilled hole 713 in the dome and in the boss 687 connects the passages 708 and 711 and, as illustrated, is lined with a bushing 714 to preclude the sealing of the hole by the diaphragm 694.

Within the passage 711 is an air filter 715 and the threaded end 716 serves to retain a reducing bushing 717 which is first horizontally and then vertically drilled to provide a vertical outlet 718.

The outlet 718 is directed into an integral boss 719 within the dome-shaped member 697. The boss is centrally drilled at 720 and the outer face thereof is machined to provide a valve seat for an electromagnetically operated plunger type valve which is similar to the trip valve mechanism illustrated for the main blast valve and omitted here for clarity.

The passage comprising the drilled holes 708, 713 and 711 thus provides a communicating channel between the central chamber 684 of the closing valve and the dome 725 thereof, and it is evident that if the opening 720 is sealed by the electromagnetically operated valve, that high pressure air entering the chamber 684 through pipe 501 will also enter the dome 725 and since the annular volume 681 is normally at atmospheric pressure, the surface area on the upper face of the diaphragm acted upon by the high pressure will be considerably greater than that upon the lower face of the diaphragm and hence the diaphragm will remain closed.

However, energization of the electromagnetic valve normally sealing the opening 720 will vent the dome 725 to the atmosphere. Thus, the pres-

sure within the dome will drop rapidly and the high pressure air within the chamber 684 will force the diaphragm up, as viewed in Figure 24, and will flow into the exhaust pipe 502, and, as will be described, thus move the disconnecting switch to the closed circuit position.

The opening 718 through which the dome 725 is charged by high pressure air has been, as previously described, directed toward the opening 720. Thus, upon the venting of the dome, the discharge of air through the opening 718 will, as in an aspirator, assist in the discharge of air from the dome 725.

The opening 720 is arranged so that the venting of the dome will occur at a much greater rate than the charging of the dome through the opening 718. As will later be described, upon the closure of the disconnecting switch contacts, the electromagnetic valve operating over opening 720 will be deenergized and permit the reclosing of this opening.

Thus the pressure will again build up in the dome 725 and with the aid of springs 705 seal the diaphragm 694 against its valve seat 693. The flow of high pressure air through pipe 502 will then cease.

A modification of this valve structure is illustrated in Figure 25. With this structure, the boss 687 may be omitted and the boss 710 on the valve dome aligned with boss 686. In this embodiment the inlet pipe 501 enters drilled opening 688 which communicates with the central chamber 684 as previously described. Drilled holes 730 and 731 in the dome and in the valve flange respectively provide a passage, as illustrated, between the opening 688 and the opening 711 in the boss 710. Thus, high pressure air is supplied to the dome 725 directly from the pipe line 688, rather than through the drilled hole 708 and 709, as in the modification shown in Figure 24. By this means the drilling operations required for the valve are considerably minimized.

The closing valve is supported upon the wall of the control box 33 by a plurality of screws which enter tapped holes 733 in a cross shaped integral extension 734 of the base of the main valve body 682.

As is illustrated in Figure 26, during the closing operation, air will flow from pipe 501 through pipe 502 into the unloading valve. From the unloading valve the high pressure air will flow through pipe 366 and cause displacement of the disconnect switch piston to the closed circuit position.

During this operation, the air on the opposite side of the piston will escape through pipe line 365 and enter the blast manifold 452 and accordingly pass out through the upper portion of the arc quencher.

During the opening of the circuit breaker, high pressure air will flow into the cylinder 362, through the pipe 365 and thus cause displacement of the piston to the left as viewed in Figure 26. To preclude pneumatic retardation of the piston, it is essential that air on the left hand side of the piston be released to the atmosphere through pipe line 366. This is accomplished by the unloading valve 490 which will now be described in greater detail with reference to Figures 21 and 22.

The main body of the unloading valve comprises the cross-shaped casting 1100 enclosing a substantially cross shaped chamber 1101. The pipe line 502 from the closing valve is tapped into a perforation 1102 in the extension 1103 of the main body. Similarly, the pipe line 366 leading

to the right hand of the disconnecting switch cylinder 361 is tapped into a perforation 1104 in the extension 1105 of the body 1100.

Two axially aligned cylinders 1106 and 1107 are formed by a bore substantially normal to the axis of the pipes 366 and 502. Operative within the cylinders 1106 and 1107 is a dumb-bell shaped piston 1110 having two hollow cylindrical members 1111 and 1112 connected by a plurality of fins 1113. The radial traverse of the fins 1113 is somewhat less than the radius of the pistons 1111 and 1112, and hence when in the position illustrated in Figure 22, there is a clear passage from pipe line 502 over the fins 1113 and into pipe line 366.

A perforation 1114 drilled through the main body wall serves as the vent for the disconnect switch cylinder. As indicated in Figure 22, the vent 1114 is completely sealed by the wall of piston 1111. However, when the dumb-bell shaped piston 1110 is displaced to the left, the vent 1114 will be uncovered and permits the flow of air from pipe 366 over the fins 1113 and out through the vent 1114.

Also, when the dumb-bell shaped piston 1110 is fully deflected to the left, the piston member 1112 completely covers opening 1115 between pipe line 502 and the center chamber 1101.

The left hand of cylinder 1106 is sealed by a cup shaped member 1116 having a rectangular flange 1117, through which suitable screws may pass. A retaining guide 1121 extends into the cylinder 1106 through the member 1116.

The guide 1121 is reduced in diameter at 1122 and threaded into a perforation in the head end of the member 1116. A nut and lock washer 1123 secure the member 1121 in place.

A compression spring 1124, retained at one end within the cup-shaped member 1116, extends into the cylinder 1106 about the retainer 1121, and enters piston member 1111 through a perforation 1125. A boss 1126 on the inner circular wall of the piston member 1111 maintains the spring in axial alignment at all times.

It is clear, therefore, that compression spring 1124 will normally provide a bias tending to drive the dumb-bell shaped piston 1110 to the position indicated in Figure 22.

The right-hand cylinder 1107 is covered by a plate 1131 which in turn is secured to the main body 1100 by a plurality of screws 1132 which also retain a cylinder head 1133 in the position illustrated.

The cylinder head 1133 is drilled and tapped at 1134 to provide securing means for pipe 1135 which as illustrated in Figure 26, connects into the main blast manifold. Plate 1131 is centrally perforated at 1136 and a screw 1137 having an enlarged head 1138 passes therethrough. The screw is secured at the right end by a nut 1141. Located circularly about the central perforation 1136 are a plurality of small perforations 1142 which are covered by the circular face 1143 of a member 1144 slidable upon the shaft of screw 1137. The cylindrical member 1144 is normally biased to the right by a compression spring 1145 which is retained between the head 1138 of screw 1137 and the enlarged circular face 1143 of said member.

The cylindrical member 1144 and the screw 1137 extend into piston extension 1112 through a perforation 1146 in the outer circular face thereof. At each end of the axial cylindrical bore, the main body is countersunk at 1151 to position a resilient annular disk 1152 which

cushions the dumb-bell shaped piston at either limit of travel. The arrangement of plate 1131 and circular member 1144 effectively provide a check valve so that air may only flow into the cross-shaped body through the perforations 1142.

A passage is provided from the lower chamber communicating with pipe line 502 to the cylinder 1107 by means of two intersecting drilled holes 1160 and 1161. As illustrated, the outer ends of these holes are plugged so that leakage from the chamber is prevented.

As illustrated in Figure 22, the unloading valve is in the normal closing position. That is, upon actuation of the closing valve, high pressure air will flow from pipe line 502 to pipe 366 and thence to the disconnecting switch cylinder to close the disconnecting switches. Upon closure of the disconnect switches, as previously mentioned, the closing air flow will cease and the unloading valve will remain in the position illustrated in Figure 22 and will be maintained in this position by spring 1124.

Upon the energization of the trip valve upon the main blast valve, high pressure air will flow into the blast manifold, and hence into pipe line 365. This last mentioned flow will enter the cylinder 362 and cause the opening movement of the disconnect switches. Simultaneously, high pressure air will enter through pipe line 1135 and will flow through perforations 1142 to displace the dumb-bell shaped piston 1110 to the left as viewed in Figure 22. This displacement will automatically cause piston extension 1112 to seal the closing line 1115 and open vent 1114 to permit the flow of air from the disconnect switch cylinder through pipe 366 and out to the atmosphere. This, as previously mentioned, will preclude pneumatic retardation of the disconnect switch piston.

Under normal operating conditions, arc extinction within the arc quencher would be accompanied by a cessation of the main air blast within the manifold 452. This would result in an immediate drop in pressure in the pipe line 1135 and hence the spring 1124 would resume control within the unloading valve and bring the dumb-bell shaped piston back to its original position.

Under abnormal operating conditions, it is possible that the closing valve may become defective and fail to close after the circuit breaker has been closed upon a faulty circuit. Under such conditions, the immediate tripping of the circuit breaker contacts would, since the closing valve would still be delivering high pressure air to the closing system, attempt to close the main contact once again. This would again result in circuit interruption and continuous pumping of the disconnecting switch.

In the electrical control described later, this would normally be prevented by a relay but on the other hand, it is conceivable that the relay controlling element may fail to operate. In this instance, the electrical control circuit will be insufficient to preclude pumping and hence the novel unloading valve illustrated in Figure 22 will assume control and prevent this undesirable condition.

Thus, should the closing pressure be maintained after the disconnect switch is closed, then initiation of the main blast and separation of the contacts within the arc quencher will exhaust the disconnecting switch cylinder. The piston 1110 will move to the left when viewed in Figure 22 but upon the cessation of the main

blast at the termination of circuit interruption, the piston will not return to the normal position because the small passage formed by drilled openings 1160 and 1161 will provide means for a flow of high pressure air from the closing line 502 to the cylinder 1107. This air will not be able to escape through the perforations 1142 because of the check valve arrangement provided at this point. Hence, it is evident that the flow of air through this small channel will retain the dumb-bell shaped piston in the left-hand position overcoming the normal bias of spring 1124. When in this position, the closing line 502 is effectively sealed within the unloading valve by piston ends 1112 and hence repeated opening and closure will be impossible.

The escaping air flowing through the passage 1160-1161 will easily be detected by an operator, thus facilitating the location of such a defective circuit breaker control system.

Summarizing the functions of the various valves, it may be seen by referring to Figures 10 and 26 that if it is desired to place the circuit breaker in operation, valve 627 is opened and the desired air pressure built up in the tank. As this pressure increases so also does the pressure in the domes of all the valves so that they are closed.

The plunger of the closing valve is then manually or automatically actuated to permit the introduction of high pressure air through the unloading valve 490 to the left side of cylinder 362 to close the disconnecting switch contacts and complete the circuit.

The main contacts are in condition for instantaneous opening if the disconnecting switches close upon a faulty line.

To cause contact opening, the plunger of the trip valve may be actuated manually or by electric means associated with over current relays in the transmission line. The displacement of this plunger will vent the main blast valve dome which in turn will permit the flow of high pressure air into the blast manifold to act upon the pistons 72 to cause contact separation and to extinguish the arc formed.

The unloading valve will be pneumatically energized at the same time to vent the closing manifold 453 to prevent retardation of the piston movement. The disconnecting switches will open subsequent to circuit interruption as a result of air flowing through pipe line 365 and then the main contacts will close.

As indicated in Figures 10 and 26, an air heating unit 896 is connected to the main air supply through an adjustable valve 896'. This heating unit, electrically energized, warms air flowing through it from the main supply. The outflowing air is fed into the pipe line 897, which as shown in Figure 17A, threads into the opening of a cored passage 898 in the main blast valve casting. The passage 898 communicates with the blast manifold at 899 and hence the heated air flows up through the arc quenching structures and out through the louvres 257. This small stream of heated air functions to maintain the arc quencher in dry condition in order that moisture which enters be prevented from freezing or injuring the insulating quality of the unit.

Since the flow of heated air is relatively small as determined by the adjustment of valve 896' it has no effect upon the normal operation of the circuit interrupter.

Various safety features are incorporated in the

circuit breaker control system illustrated in Figure 26 which prevent circuit breaker operation during undesirable conditions and which automatically cause interruption when necessary.

A switch 981 is automatically controlled by the pressure within the pipe line 451 and the air storage tank 31 at all times. When the tank pressure falls below the minimum value required for safe interruption, this switch automatically operates to prevent energization of the trip valves 10 and so prevents an attempted circuit interruption.

The tank pressure switch 981 also prevents closing of the circuit breaker by the energization of the coil of the closing valve 500 when the tank pressure is low. The tank pressure switch 981 controls the operation of contact 1004 to close this contact only when the tank pressure is correct, thereby preventing closing of the breaker under any other condition.

A safety valve 982 is also connected in the line 451 and automatically operates to bleed off air when the tank pressure rises above a maximum safe value.

A pneumatically operated switch 983 is included in the disconnect switch opening line 365 and thus is operable by the pressure within the blast manifold 452.

The electrical control circuit for the air blast circuit breaker hereinabove described is schematically illustrated in Figure 27 and reference is now made thereto.

The electrical circuit is energized by a source which may be obtained from batteries or from rectifiers energized by the alternating current supply. This direct current source is schematically represented in Figure 27 by the positive and negative bus bars 1000 and 1000' respectively.

The closing valve coil 500' and the trip valve coil 613 are schematically indicated in Figure 27.

A limit switch disposed within the control cabinet 33 is operable by the disconnecting switch operating members, and has three sets of contacts 1001, 1002 and 1003, arranged so that when the disconnecting switch is at its fully closed position, the contacts 1001 and 1003 will open and the contact 1002 will close. In the fully open position of the disconnecting switch, contacts 1001 and 1003 will close and contact 1002 will open.

The previously mentioned blast pressure switch 983 in the disconnecting switch closing air line 365 contains the contacts 1017 and 1018, the latter of which will close upon the initiation of a blast. Simultaneously, contact 1017 will open and, as will be described, will preclude operation of the closing circuit. Lack of tripping pressure in the line 365 will cause contacts 1018 to open and contacts 1017 to close.

The tank pressure switch 981 previously described contains the contacts 1004 which are closed when the storage tank pressure is sufficiently high to provide for proper circuit breaker operation. When however, the tank pressure drops below this safe value, the tank pressure switch contacts 1004 open.

Thus, provided that tank pressure contacts 1004 are closed, the circuit breaker may be closed by closing switch contacts 1012. Upon closure of contacts 1012, a circuit is completed from wire 1000, through tank pressure switch 1004, contacts 1012, wires 1013, 1014, and coils 1015 and 1016. Contacts 1017 and 1001 are in series with coil 1015, but since these are normally closed, they will not interfere with the energization of coil 1015.

Coils 1015 and 1016 are wound upon the end poles 1021 and 1040 of an E-shaped magnet core having a coaxing magnetic member 1025 pivotally supported upon pin 1026 as schematically indicated in Figure 27. The upper coil 1015 is more powerful than lower coil 1016 and hence upon the simultaneous energization of both coils, magnetic member 1025 will rotate counterclockwise as viewed in Figure 27, to engagement with the upper member 1027.

This rotation of member 1025 will be accompanied, through the agency of rod 1028, by the closure of contacts 1031 and 1032. The closure of contacts 1032 will complete a circuit directly from line 1000 through coils 1015 and 1016 and wire 1023 to line 1000. Hence the closing operation will continue independent of the intermediate release of closing contacts 1012. Closure of contacts 1031 will through tank pressure contacts 1004 and protective resistor 1005 energize the closing magnet coil 500' upon the closing valve.

Accordingly, the closing valve will act to permit high pressure air to flow from the storage tank 31 through the unloading valve and into the disconnecting switch cylinder to close the disconnecting switch at which time the circuit breaker will be in operative condition.

Upon the completion of the closing movement 30 of the disconnecting switch contacts 1004 open and deenergize coil 1015 and thus member 1025 will spring back to its central position, deenergizing closing coil 500'. If the closing switch is at this time still in the closed position, only coil 35 1016 will be energized and armature 1025 will rotate clockwise into contact with the lower pole 1040 of the E-shaped magnet. This as will be described, will preclude pumping of the circuit breaker if closed upon a fault.

40 In order to manually trip the circuit breaker, contacts 1038 are closed which immediately completes a circuit from line 1000 through tank pressure switch 1004, contacts 1039, closed contacts 1002, trip coil 613, protective resistor 1045 to line 45 1000'. The energization of trip coil 613 will, as previously described, permit the flow of high pressure air into the blast manifold and hence cause the separation of the contacts within the arc quencher and the subsequent displacement of the 50 disconnecting switch piston. The increased pressure in pipe line 365 will cause the actuation of blast pressure switch 983 and thus the opening of contacts 1017 and the closing of contacts 1018. The closure of contacts 1018 will short circuit the contacts 1039 and hence, when once initiated, 55 circuit interruption will go to completion even if the contacts 1039 are separated by the operator. The opening of contacts 1017 will render the coil 1015 inoperative even if closing contacts 1012 are 60 accidentally closed.

Thus it may be seen that the blast pressure switch provides an electrical interlock to ensure proper operation of opening and closing circuits.

Upon completion of the tripping operation, that 65 is, the final opening of the disconnecting switch, the contacts 1002 open to deenergize the trip coil 613 and the contacts 1001 and 1017 close to again place the closing circuit in an operative position.

Automatic tripping of the circuit breaker is 70 accomplished by overload relays such as 1052 operating in the trip circuit described above. As illustrated, in Figure 27, three overload relays, one for each phase, are illustrated.

Each pole of the overload relay is actuated by 75 a solenoid coil 1051 energized from a current

transformer 1160 in one phase 1061 of the three phase circuit. Upon the occurrence of a circuit fault, the energization of coil 1051 will cause the closure of contacts 1056 and complete a circuit from line 1000, contacts 1004, through wires 1059 and 1059 through coil 1064, contacts 1056 and 1052, and through trip coil 613 to line 1062'. The energization of coil 613 will, as previously described, cause circuit interruption. The energization of coil 1064 will cause normally open contacts 1063 to close and short circuit contacts 1056. Thus circuit interruption will be completed even if the fault disappears immediately after its inception.

If the closing control switch 1012 is actuated when faulty conditions exist within the circuit in which the circuit interrupter is connected, the normal closing procedure previously described will occur. Thus, the closing coil will be energized and permit the introduction of air to cause displacement of the disconnecting switch operating piston.

When the disconnecting switches close, however, the over current relay coil 1064 will be instantaneously energized to cause the energization of the trip coil 613, and hence the opening of the breaker will be initiated.

Since the time required to effect the closing and opening of the circuit interrupter is comparatively short, it is possible that the operator may still be holding switch 1012 in its closed position.

It is to be noted that when the disconnecting switches complete their closing movement, that the switch 1001 opens and hence the operating coil 1015 is deenergized immediately whereas the coil 1016 remains energized if the operator is still maintaining contacts 1012 in their closed position. It will be understood that although coil 1015 is more powerful than coil 1016, once coil 1016 has pulled armature 1025 to its pole, it is effective to hold it there in opposition to the actions of coil 1015. The coil 1016 will thus assume control of the movement of contacts 1032 and 1031, the last mentioned of which is in the closing coil circuit.

The coil 1016 will operate to maintain contacts 1032 and 1031 in the open circuit position regardless of subsequent energization of the coil 1015. Thus when the disconnecting switches open to complete circuit interruption, the closure of contacts 1031 in the operating coil circuit will not permit the repetition of the closing cycle even though the closing switch 1012 has its contacts engaged.

Therefore, it may be seen that this type of closing relay including the coils 1015 and 1016 will preclude the "pumping" or repeated operation of the circuit breaker under faulty conditions.

When the operator releases switch 1012 the holding coil 1016 is deenergized and the contacts 1032 and 1031 are once more placed under the control of the coil 1015 and the circuit interrupter is in condition for closing if such is desired.

Several pilot lights may be included in the electrical circuit as shown in Figure 27. Thus a lamp 1070 is connected in series with the tank pressure switch 1064 across the lines 1000-1000' to indicate when illuminated that the tank air pressure is at a safe operating value.

Lamp 1075 is in circuit with the trip coil 613 and contacts 1002. Thus when the circuit breaker is in operation and contacts 1002 are closed, the lamp 1075 will glow. The current for this lamp flows through the trip coil 613, but since the lamp

resistance is high, this current will not interfere with the normal operation of this coil.

Lamp 1074 is in series with contacts 1003 and this circuit is across the lines 1000-1000'. Contacts 1003 will close when the disconnecting switch is open and thus by its illumination indicate that the main circuit is open.

Accordingly, it may be seen that the novel electrical control circuits of Figure 27 when combined with the pneumatic control circuit, Figure 26, provides a novel and highly efficient and flexible control system for the operation of a circuit interrupter.

The various valves illustrated for governing the flow of a high pressure gas may be modified to fit a particular application. This applies to the structure of the arc quencher and the electrical circuits utilized. Hence since many modifications of the specific disclosures hereinabove set forth will be immediately evident to those skilled in the art, I prefer to be bound only by the spirit and scope of the appended claims.

I claim:

1. In a fluid blast circuit breaker main contact members, a disconnect switch member, a source of fluid under pressure, a piston controlled by fluid from said source for operating said switch member to open and to closed position, a valve operative when open to permit the flow of fluid from said source to said piston for operating said switch member to open position, an electromagnet operative when energized to control the opening of said valve, a second valve for controlling the flow of fluid from said source to operate said switch member to closed position, an electromagnet operative when energized to control said second valve, and means controlled by fluid from said source for disconnecting said main contact members, said piston being thereafter operated to operate said disconnect switch member to open position, means operative when current ceases to flow in the circuit controlled by said circuit breaker for operating said main contacts to re-engaged position, means for controlling the energization of the last mentioned electromagnet to effect reclosure of said disconnect contacts, and means for rendering said last mentioned means ineffective as soon as said disconnect contacts are closed to prevent pumping of said circuit breaker.

2. In a fluid blast circuit breaker, a switch member, a source of fluid under pressure, means controlled by said fluid under pressure for operating said switch member to open and closed position; a valve mechanism operable when open to permit the flow of fluid from said source for closing said first mentioned means to effect operation of said switch member to closing position, means including an electromagnet operable when said electromagnet is energized to open the said valve; contact means controlling the energizing circuit of said electromagnet and operated to open said circuit on the initiation of a blast from said source of fluid pressure for operating said switch controlling means to open said switch, said contact means when open preventing energization of said electromagnet, contact means included in the circuit of said electromagnet and operated to open position when pressure of said source is below a predetermined value, manually operable means for controlling the energizing circuit for said electromagnet and means for deenergizing said electromagnet when said switch has been fully closed independent of the position of said manually operable means.

3. In a fluid blast circuit breaker, a switch member, a source of fluid under pressure, means

controlled by said fluid under pressure for operating said switch member to open and closed position; a valve mechanism operable when open to permit the flow of fluid from said source for closing said first mentioned means to effect operation of said switch member to closing position, means including an electromagnet operable when said electromagnet is energized to open the said valve; contact means controlling the energizing circuit of said electromagnet and operated to open said circuit on the initiation of a blast from said source of fluid pressure for operating said switch controlling means to open said switch, said contact means when open preventing energization of said electromagnet contact means included in the circuit of said electromagnet and operated to open position when pressure of said source is below a predetermined value manually operable means for controlling the energizing circuit for said electromagnet, and means for deenergizing said electromagnet when said switch has been fully closed independent of the position of said manually operable means, said means comprising a relay having two windings one of which is energized over a circuit controlled by the pressure of said fluid supply and the position of said switch

and the other of said windings having a self-locking circuit when said first winding is energized, said second winding being operative to open the circuit of said electromagnet when said first winding is de-energized.
